SWITCH AND SIGNAL CONTROL SYSTEM
FOR RAILROADSClark A. Pickell, Rochester, N. Y., assignor to
General Railway Signal Company, Rochester,
N. Y.

Application July 6, 1939, Serial No. 282,999

5 Claims. (Cl. 246—3)

This invention relates to switch and signal control systems for railroads, and it more particularly pertains to the control, by use of a code type communication system, of switches and signals remotely located from an entrance-exit type control machine at a control office.

An entrance-exit type control machine is generally provided with a control panel within convenient reach of an operator, upon which is constructed a miniature track diagram of the track layout in the field for which the machine is provided. The entrance and exit ends of routes in the track layout are defined by the location of wayside signals, each route extending from an entering signal to another signal for governing traffic in the same direction, or to the limits of the track sections governed by the control machine, as the case may be. Control buttons, or equivalent contactors, for the designation by an operator of each entrance and exit point are provided on the control panel along the miniature track diagram at points corresponding to the respective entrance and exit ends of each route, and suitable indication means is provided along the track diagram for conveying to an operator an indication as to which routes are established, the condition of occupancy of the various track sections, and the condition of the signals.

In accordance with the present invention such a control machine is connected by means of a suitable code type communication system, such, for example, as the communication system shown in the patent to Judge et al., Patent No. 2,082,544, dated June 1, 1937, with an entrance-exit type of switch and signal control system at a remote track layout which can be, for example, of the type shown in the patent to A. Langdon, Patent No. 2,148,865, dated February 28, 1939, and in the application of Wight and Langdon, Ser. No. 245,384, filed December 13, 1938 now U. S. Patent 2,219,502, granted Oct. 29, 1940.

The switches and signals relatively close to each other, together with the apparatus for their control, constitutes what is conveniently called a field station, and each field station is subdivided into a plurality of control stations, each of which is made up of control apparatus associated with a particular switch or signal location. Thus, one control station is provided for each signal location and for each track switch, although it is to be understood that modifications of this grouping can be provided if such is the requirements of practice.

The communication system is operative through various cycles of operation, some of

which for the transmission of controls from the control office to the field are called "control cycles," and others for the transmission of indications of the devices at the field stations to the control office are called "indication cycles," each cycle being characterized by the energization of a line circuit extending between the control office and the field stations with a series of time spaced electrical impulses. It can also be provided by "duplex" operation that indications can be transmitted under certain conditions at the same time in which controls are being transmitted from the control office.

Each control cycle is composed of a series of time spaced impulses forming a complete composite code. The first part of that code is used to identify the particular field station for which the controls are to be transmitted; the second part of that code is used to identify the control station for which the controls are intended; and the last part of that code is used to define in the field the control designated in the control office for an entrance or exit point or track switch.

An object of the present invention is to provide that only one entrance or only one exit point can have its code transmitted during one control cycle, thus requiring the transmission successively of two cycles of operation for the complete establishment of any route in accordance with the designation of the entrance and exit ends of that route. An advantage of such a mode of operation is that transmission of a cycle for defining an exit point occurs subsequent to the transmission of a cycle for defining an entrance point which allows a sufficient period of time for the conditioning of certain relays in the field which are required for the proper reception and storage of a code defining an exit point for that route.

Another object of the present invention is to provide a simple means for rendering the transmission of controls effective upon actuation of the contact means on the control panel for designation of controls to be transmitted, such initiation of the communication system being effective only after the contact means causing such initiation has reached its new operating position. In other words, the initiation of the communication system for the transmission of controls is effective only when an operator has actuated a contactor on the control panel to a new operating position, thus providing assurance that the controls to be transmitted are designated before initiation of the system becomes effective.

Another object of the present invention is to provide a means whereby the establishment of each route in the field is effective responsive to the designation by an operator at the control office of the extreme ends of that route only, even if there are intermediate signals included between the route ends designated. The establishment of a route including one or more intermediate signals responsive to the designation of the extreme entrance and exit ends only of such route is called, for convenience, "through route" or "end-to-end" control.

Another object of the present invention is to provide that the designation of either an entrance or an exit control by an operator initiates the system into a cycle of operation for the transmission of such control, and as long as the respective entrance and exit points for each route are designated in their proper order, (the entrance end of each route designated prior to the designation of the exit end of that route) such order is always maintained in the transmission during successive control cycles for respective entrance and exit controls, even if both the entrance and exit ends of a route are designated by an operator at a time when the communication system is not immediately available for the transmission of such controls.

It is believed that other objects, purposes and characteristic features of the present invention will be more readily understood upon reference to the accompanying drawings and as they are apparent at various points in the description of the present invention.

In describing the invention in detail, reference is made to the accompanying drawings in which corresponding parts are designated by corresponding reference characters, in which those parts having similar features and functions are designated by like letter reference characters which are generally made distinctive either by distinctive exponents or by preceding numerals, and in which:

Fig. 1 illustrates diagrammatically, the general organization of a system provided in accordance with the present invention;

Figs. 2A, 2B and 2C, when placed side by side, illustrate the means provided in the control office for setting up codes to be transmitted to the field in accordance with the actuation of buttons and levers on the control machine;

Fig. 3 illustrates the means provided at the control office for the stepping impulsion of the line circuit, and the reception of indications for the communication system used in this embodiment of the present invention;

Fig. 4 illustrates the means provided at one of the field stations for the reception and decoding of codes transmitted from the control office, and also illustrates means provided at such field station for the transmission of indications to the control office;

Figs. 5A and 5B, when placed side by side, illustrate circuit means by which the decoding of code messages is transferred upon execution to switch and signal application relays;

Figs. 6A and 6B, when placed side by side, illustrate the track layout for which the control apparatus illustrated in Figs. 2A, 2B and 2C, is provided, together with an entrance-exit type of self-selecting circuit network system for establishing the various routes in accordance with the controls designated by an operator in the control office; and

Fig. 7 illustrates certain typical circuits relative

to the control of the switches and signals at the various control stations.

Reference is made from time to time during the description of the present invention to relays and devices of a similar nature by use of letter reference characters associated with such parts without their preceding numerals and exponents. It is to be understood that such a reference applies to any parts designated in the drawings by letter reference characters which are similar except for preceding numerals and exponents.

The various parts and circuits constituting the embodiment of the present invention have been shown diagrammatically and certain conventional illustrations have been employed for the purpose of facilitating the explanation of the present invention and for the purpose of simplifying the drawings, rather than for illustrating the specific construction and arrangement of parts that would be employed in practice. Thus, the various relays and their contacts are illustrated in a conventional manner, and symbols are used to indicate connections to the terminals of batteries or other sources of electric current instead of showing all of the wiring connections to such terminals. In order to illustrate more clearly the arrangement of circuits employed in accordance with the present invention some relays have been shown in more than one drawing, and some relays have the circuits shown for their different windings on different drawings, the corresponding relays throughout the different drawings being readily identified by like nomenclature.

The symbols (+) and (-) are employed to indicate the positive and negative terminals respectively of suitable batteries or other sources of direct current, and the circuits with which those symbols are used always have current flowing in the same direction. If alternating current is used in place of direct current, the particular symbols shown are to be considered as relative instantaneous polarities.

Apparatus

45 *Track layout.*—With reference to Figs. 6A and 6B, the track layout chosen for the embodiment of the present invention consists of a main stretch of track to which are connected two other tracks by means of the track switches 2TS and 3TS respectively.

50 Signals are provided for governing traffic through the track layout in each direction, signals 4, 4C, 5 and 6 being provided for governing east bound traffic to the right, and signals 7, 8 and 9 being provided for governing west bound traffic to the left.

55 The signals are illustrated as being of the color light type having individual color lamp units, the top lamp providing a green clear indication, and the lower lamp providing a red danger indication for each signal. It is to be understood that a yellow indication for caution can as well be provided, in accordance with the requirements of practice, and that other types of signals such, for example, as semaphore and search light signals can as well be used.

60 The track switches 2TS and 3TS are provided with switch machines 2SM and 3SM respectively which provide the power operation of those track switches in accordance with the positions of the track switches required. Various types of switch machines can be used, such, for example, as the type disclosed in the patent to W. K. Howe, Patent No. 1,466,903, dated September 4, 1923. Each switch machine is assumed to have

included therewith suitable overload protection devices and other control apparatus commonly employed in the control of the switch machine motors, such as is shown, for example, in the patent to W. H. Hoppe et al., Patent No. 1,877,876, 5 dated September 20, 1932.

The track layout is divided into two track sections 2T and 3T which are provided with track circuits in the usual manner for control of the track relays 2TR and 3TR respectively. It is 10 to be understood that the track switches 2TS and 3TS are properly bonded to provide fouling protection in the usual manner.

Each track switch has associated therewith a point detector relay WP of the polar neutral 15 type energized with one polarity when that particular track switch together with its switch machine is locked in a normal position and energized with the opposite polarity when that track switch and its switch machine are locked in a 20 reverse position. Each relay WP is deenergized whenever its track switch and/or its switch machine are unlocked or out of correspondence. Such control of each relay WP is provided by 25 contact selections which include contacts of a point detector contact mechanism of the type shown, for example, in the patent to C. S. Bushnell, Patent No. 1,517,236, dated November 25, 1924.

Control Machine.—The control machine used in accordance with the present invention can be 30 of the type shown, for example, in the patent to J. F. Merkel, Patent No. 2,145,798, dated February 28, 1939, in which a vertical control panel is provided within convenient reach of an operator. Upon the control panel is constructed a miniature track diagram to correspond with the track 35 layout in the field for which the system is provided, and suitable indicator lights are disposed along the track diagram to provide sufficient indications to keep an operator well informed as to the various conditions existing in the field 40 pertinent to the condition of occupancy of the various track sections, the routes established, and the condition of the various signals. Inasmuch as this invention is primarily related to the control of the switches and signals in the field in accordance with the actuation of control 45 devices by an operator at the control office, such indications have not been shown in this disclosure except for one indicator lamp XCHE (see Fig. 2B), for the purpose of simplification, but it is to be understood that the indications are provided in a suitable manner such as is shown, for example, in the application of R. M. Phinney, Ser. No. 216,459, filed June 29, 1938.

For designation of the entrance end of each route, a control button NB is provided on the control panel at a point in the miniature track diagram corresponding to an entering signal for that route in the field. That is, for example (see Fig. 2A), the entrance button 4NB is provided on the miniature track diagram at a point corresponding to the location of signal 4 (see Fig. 6A) at the track layout in the field. Each of the entrance buttons NB is of the push-pull type, and is biased to a center position with respect to push-pull operation, and, where another operating position is required for the button, such as is required for the control of a call-on signal, the button can be rotated from its normal center position to an operating position in which it will remain until manually restored to its normal position. The construction of a control button to provide such distinctive positions can be

5 provided in any suitable manner, such, for example, as that shown in the application of J. F. Merkel, Ser. No. 158,720, filed August 12, 1937, now U. S. Patent 2,223,126, granted Nov. 26, 1940.

Each of the exit buttons XB is used for designation of the exit end of a route and is disposed on the miniature track diagram at a point corresponding to the exit point at the track layout with which it is associated. Each exit button XB is of the self-restoring type, having an operating contact closed when the button is depressed.

It is to be understood that other types of contacts than the specific types shown and described in this embodiment of the invention can be provided, in accordance with the requirements of practice, and that the entrance and exit buttons NR and XR respectively for each signal location can have their contacts combined into one button providing the required number of distinctive operating positions, and it is to be further understood that a single button can be used for each route end for designation of both entrance and exit points in combination with circuit means for distinguishing between the actuation of a control button for the designation of an entrance or an exit point such as is shown, for example, in the application of R. M. Phinney, Ser. No. 216,459, filed June 29, 1938.

An auxiliary switch control lever SML is provided on the control panel for each of the track switches so that an operator can cause the positioning of that track switch irrespective of the system for the establishment of routes in accordance with the designation of entrance and exit points. Each auxiliary switch control lever SML has a center neutral position in which it is ineffective for governing the operation of its associated track switch, an upper operating position in which it causes the operation of its track switch to a reverse position, and a lower operating position in which it causes the operation of its track switch to a normal position. Each lever SML is maintained in either of its three operating positions until actuated to another position by an operator.

Control office relays.—At the control office entrance relays NR are responsive to the designation of their particular entrance points by an operator, and, when picked up, they are maintained energized until a cycle of operation of the communication system is completed for transmission of controls to the field in accordance with such entrance designation. For a similar purpose a relay CNR is provided for each call-on signal governing entrance to each route. A change relay NCH is provided for each entrance point, and is picked up when the designation of that entrance point is effected to initiate the system into a cycle of operation.

Upon designation of an exit point by an operator an exit change relay XCH is energized to cause the transmission of controls for defining that particular exit point in a manner which corresponds with the initiation of the system in accordance with the energization of each entrance change relay NCH.

As a part of the communication system certain relays are provided in the control office which correspond in character and function to relays bearing similar nomenclature shown in the above mentioned patent to Judge et al. Patent No. 2,082,544, dated June 1, 1937, and, in view of the fact that a detailed description of such relays and their control circuits is shown in that

patent, reference can be made thereto for a description of the communication system as used in accordance with the present invention. Thus, in accordance with that Judge et al. patent, relays CHP, CDS, CD, C, FC, NC, PC, E, EP, F, FP, 2FP, SA, 2SA, DV, MF, NB, VP, IV, 2V, 3V, 4V, 5V, 6V, IV and LV are provided at the control office.

A relay XCHP is provided in the control office for the purpose of preventing from becoming effective the designation of entrance and exit points for a second route when the entrance and exit points designated for a first route have not yet been transmitted. Such relay XCHP is normally energized and is dropped away whenever a change relay XCH is picked up for an exit point designated. As a means for cancelling any controls designated which have not yet been transmitted, a cancel button CAN is provided which, when depressed, causes the restoration to normal of the relays associated with the initiation of the communication system.

Field station relays.—The field station relays (see Fig. 4) include certain relays essential to the communication system such as relays F¹, FP¹, SO¹, SOS¹, SA¹, SB¹, PB¹, PF¹, IV¹, 2V¹, 3V¹, 4V¹, 5V¹, 6V¹, IV¹, LV¹ and VP¹.

A bank of decoding relays composed of relays NS for decoding negative impulses and PS for decoding positive impulses is provided at the field station, one PS relay and one NS relay being provided for each step in the field used for the reception of control and control station impulses. The relays PS and NS are picked up during the reception of controls as they are received, and those relays are maintained energized when picked up until after execution of the controls thus decoded at the end of that cycle of operation.

Each control station in the field has a control station relay ST which is energized during a control cycle when the controls of that cycle are for that particular station. Thus, for example, if the controls designated are for the route end at signal 5, the station relay 1ST (see Fig. 5B) is picked up to correspond with the controls transmitted for station 1 as shown in Fig. 1.

An entrance relay NR¹ is provided for each entrance point and an entrance relay CNR¹ is provided for each entrance point that has a call-on signal. The entrance relays NR¹ and CNR¹ are energized during the execution period at the end of the control cycle in accordance with the designation of corresponding entrance points at the control office. Such entrance relays are maintained energized when once picked up dependent upon the condition of occupancy of various track sections in the field and/or dependent upon the position of the stop relay B, which can be energized responsive to the designation in the control office by an operator for the restoration of a particular signal to stop or a particular entrance relay to its normally deenergized position.

A relay XZ having slow drop away characteristics is provided for each exit point in the field, and it is energized momentarily at the end of a control cycle for designation of its exit point to cause the picking up of an exit relay XR (see Figs. 6A and 6B), such exit relays XR being energized only if a route is available between that exit point and an entrance point which has been designated on a prior cycle of operation of the communication system.

A route is selected in the field in accordance

with the selective energization of normal and reverse switch control relays N and R which have their control circuits selected in accordance with relays Y which are energized for track switches trailed normal in an available route from each designated entrance point.

Response to the picking up of a normal relay N or a reverse relay R for each track switch, a polar neutral switch control relay WZ (see Fig. 10) is energized with the proper polarity to cause the positioning of its track switch if such positioning is safe and proper as determined by the lock relays L and LS, the energization of such lock relays for allowing the positioning of the track switch being dependent upon the route and detector locking.

When each of the track switches has completed its operation in accordance with designated controls, a correspondence relay NCR or RCR, dependent upon the position of the track switch, is energized, and the lock stick relay LS for that track switch is dropped away to close a branch of the circuit network for the energization of a relay G provided for each signal for governing the indications such signal is to display.

In accordance with the principles of the self-selecting network system they have been set forth in the application of S. N. Wight and A. 30 Langdon, Ser. No. 245,384, filed December 13, 1938, a relay XP is provided for each intermediate signal that can be included between extreme ends of a route designated for the establishment of a route in accordance with the system of end-to-end control.

Having thus considered the apparatus provided in accordance with the present invention and its general application, a more specific description of the principles of the system and 40 the mode of operation will be hereinafter set forth upon considering various typical conditions of operation of the system.

Operation

45 Inasmuch as the communication system used in accordance with the present invention is substantially as shown and described in the patent to Judge et al., Patent No. 2,082,544, dated June 1, 1937, reference can be made to that patent 50 for the specific description of the communication system omitted in the present disclosure. The general operation of the communication system will, however, be hereinafter pointed out in a manner believed sufficient for an understanding 55 of the present invention, and such improvements in the communication system as are provided by the present invention will be specifically described.

Communication system general.—As has already been pointed out, the communication system is operable through various cycles of operation, each cycle being composed of a series of electrical impulses. The impulses are time spaced and of a selected polarity, such impulses 60 being impressed at the control office upon a line circuit extending from the control office to the field stations. The control line circuit to which the impulses are applied is composed of two line wires of which, for the purpose of describing 65 the present invention, one wire is called the "control line" and the other wire is called the "return line". The control line and return line wires are connected at the most remote field station and the control line wire 20 (see Figs. 3 and 4) includes in series a three-position polar

relay F at the control office and a similar relay F¹ at the field station illustrated in Fig. 4, and a relay F (provided with a proper exponent) for each of the other field stations included in the system. For the purpose of referring from time to time to the polarity of the line circuit reference is made to the positive or negative energization of such circuit, and that reference is to be understood as the connection of the positive or negative battery terminal respectively to the side of the line circuit at the control office including the control line wire 20.

The organization of the communication system is such that when it is inactive, most of its relays are normally deenergized and the system is considered in general at such time to be in a "period of rest." The initiation of a control cycle at the control office, upon designation by an operator of a control to be transmitted, causes energization of the line circuit for a first impulse with a selected polarity, dependent upon the code to be transmitted. Such initial energization of the line circuit is known as the conditioning period in which certain normally deenergized relays at the control office and at each field station are energized to condition the system for the purpose of communicating the controls designated. After such conditioning has been completed an impulsive relay is picked up at the control office to cause the first period of deenergization of the line circuit during the cycle, commonly known as the first "off" period. During such "off" period the first of the stepping relays V is picked up at the control office and at each field station that remains in communication with the control office, and the picking up of such a stepping relay causes the dropping away of the impulsive relay at the control office which closes the line circuit for the second period of energization during the cycle, which is conveniently called the first "on" period. Thus, the communication system is operated step-by-step through each cycle, one stepping relay being picked up during each "off" period, and an element of the code being applied by means of selected polarity, as will hereinafter be pointed out, to the line circuit during each "on" period. After the stepping, during a cycle of operation, has been completed, the system enters a clearing-out period, during which time the controls decoded at the field station selected for the reception of controls, are executed, and during which restoration of the relays to a period of rest is effective.

Suitable lockout means is provided at the control office whereby the transmission of controls selected for one cycle of operation cannot be interrupted by the designation of other controls to be transmitted.

The stepping at each of the field stations continues to be effective during a control cycle only so long as the predetermined code to which that field station is responsive for field station selection corresponds with the code characters impressed upon the line circuit at the control office. Thus, it is obvious that the series of impulses at the control office carries a message which, through the process of elimination, maintains only one particular field station in communication with the control office for the reception of the remainder of the impulses of that cycle.

Normal conditions.—With reference to Figs. 2A, 2B, 2C and 3 the relays of the system at the control office are all illustrated under normal

- conditions to be deenergized with the exception of relays 2CH and XCHP shown in Fig. 2B. Relay 2CH is normally maintained energized by the energization of a stick circuit closed from 5 (+), through a circuit including back contact 22 of relay 2CD, front contact 23 of relay 2CH, and lower winding of relay 2CH, to (-). Relay XCHP is normally maintained energized by the energization of a circuit closed from (+), through 10 a circuit including back contact 24 of relay 5XCH, back contact 25 of relay 4XCH, a back contact of a relay XCH for each of the other exit points as represented on the drawing by an X, and winding of relay XCHP, to (-).
- 15 At the field station, under normal conditions, the relays associated with the communication system are deenergized with the exception of the change relay CH¹ which is normally maintained energized until its deenergization by a change in the position of one of the devices to be indicated causes the initiation of an indication cycle.
- The relays associated with the self-selecting network in the field and the control of the 25 switches and signals as shown in Figs. 6A, 6B and 7 are normally deenergized with the exception of the track relays TR, the lock relays L and LS, and the correspondence relays NCR. The lock relay 2L (see Fig. 7) is normally maintained 30 energized by a circuit closed from (+), through a circuit including front contact 26 of relay 2ES, front contact 27 of relay 2TR, front contact 28 of relay 2WS, winding of relay 2L, and front contact 29 of relay 2L, to (-). Relay 2LS is normally energized by a circuit closed from (+), through a circuit including front contact 30 of relay 2L, back contact 31 of relay 2WZ, and winding of relay 2LS, to (-). The correspondence relay 35 2NCR is normally energized by a circuit closed from (+), through a circuit including back contact 32 of relay 2R, winding of relay 2NCR, polar contact 33 of relay 2WP in a right hand position, and front contact 34 of relay 2WP, to (-).
- 40 45 The track switches are assumed to be in the position required for the last route established, which, for the present disclosure, has been assumed to be a through route on the main track.
- Initiation of the system.*—When an operator 50 wishes to designate controls to be transmitted to a field station, he first checks his indicator lamp XCHE, which, if extinguished indicates that entrance and exit controls designated previously have been transmitted, and then he proceeds to 55 designate the controls which he wishes to have transmitted to a field station. He may designate controls for restoration or control for the switches when the indicator lamp XCHE is illuminated, but he must not designate entrance or exit controls unless the indicator lamp is extinguished.
- To consider the designation of a particular typical type of a control to be transmitted, assume that an operator designates an entrance point at signal 5 for a route to be established by 60 the depression of button 5NB, when the normal conditions of the system exist as they have been shown and described. The depression of button 5NB causes the energization of the entrance relay 5NR, and the picking up of relay 5NR causes the picking up of the relay 5NCH for the initiation of the control cycle. Relay 5NCH causes the picking up of relay CHP, and relay CHP in picking up causes the energization of relay C. The 65 70 75 relay 5CD is picked up after relay C, and upon

picking up, it closes its stick circuit which includes in series relay CDS which is picked up at that time. When relay 5CD is picked up, the relay PC is energized to cause the positive energization of the line circuit for the conditioning period of a control cycle to be transmitted. Each of the above relays energized at the start of the control cycle is maintained energized throughout the cycle with the exception of relay 5NCH which is dropped away upon the picking up of relay 5CD.

To consider in detail the circuits by which the above mode of operation is effected, relay 5NR is energized when the button 5NB is depressed by a circuit closed from (+), through a circuit including contact 36 of button 5NB closed in a depressed position, and upper winding of relay 5NR, to (-). Upon the picking up of relay 5NR, a pick-up circuit is closed for relay 5NCH from (+), contact 36 of button 5NB in a depressed position, front contact 37 of relay 5NR, upper winding of relay 5NCH, wire 38, and front contact 39 of relay XCHP, to (-). A stick circuit is closed for relay 5NCH upon the picking up of that relay from (+), through a circuit including back contact 40 of relay 5CD, front contact 41 of relay 5NCH, lower winding of relay 5NCH, wire 42, and normally closed contact 43 of cancel button CAN. Such stick circuit maintains relay 5NCH energized until relay 5CD is picked up or the cancel button CAN is depressed.

When relay 5NCH is picked up, a stick circuit is closed for relay 5NR from (+), through a circuit including front contact 70 of relay 5NCH, front contact 71 of relay 5NR, and lower winding of relay 5NR, to (-). Energy is also applied to that stick circuit at front contact 40 of relay 5CD to provide that relay 5NR is maintained energized until the end of the cycle for the transmission of the controls selected by that NR relay. The stick circuit is maintained closed because relay 5NCH is maintained picked up until after relay 5CD is picked up.

The picking up of relay 5NCH causes the picking up of relay CHP by the energization of a circuit closed from (+), through a circuit including back contact 44 of relay SA (see Fig. 2C), back contact 45 of relay FC, upper winding of relay CHP, wire 46, and front contact 47 of relay 5NCH, to (-). Relay CHP is maintained energized until the end of the cycle by a stick circuit closed from (+), through a circuit including back contact 48 of relay LV (see Fig. 2C), front contact 49 of relay CHP, and lower winding of relay CHP, to (-). Energy is also applied to that stick circuit at back contact 50 of relay EP to prolong the period in which relay CHP is maintained energized in case relay LV is picked up to open back contact 48 before the end of the last impulse.

Upon the picking up of relay CHP a circuit is closed to cause the picking up of relay C from (+), through a circuit including back contact 51 of relay SA, front contact 52 of relay CHP, and winding of relay C, to (-). A stick circuit is closed for relay C when that relay is picked up to maintain it energized throughout the cycle from (+), through a circuit including back contact 53 of relay 2SA connected in multiple with front contact 51 of relay SA, front contact 54 of relay C, and winding of relay C, to (-). That stick circuit is maintained closed throughout the cycle because relay SA is picked up prior to the

energization of its repeater relay 2SA, and both relays are maintained picked up because of their slow action throughout the cycle of operation.

Upon the picking up of relay C, relay 5CD is picked up by the energization of a circuit closed from (+), through a circuit including back contact 48 of relay LV, back contact 55 of relay 2SA, front contact 56 of relay C, back contact 57 of relay CDS, wire 58, front contact 59 of relay 5NCH, lower winding of relay 5CD, wire 42 and normally closed contact 43 of cancel button CAN, to (-). When relay 5CD is picked up, a stick circuit is closed for that relay including the winding of relay CDS, from (+), through a circuit including front contact 60 of relay CHP, winding of relay CDS, wire 61, front contact 62 of relay 5CD, upper winding of relay 5CD, wire 42, and normally closed contact 43 of cancel button CAN, to (-). The picking up of relay CDS prevents the picking up of any other CD relays during that cycle of operation by opening the circuit for such relays at back contact 57.

Upon the picking up of relay 5CD energy is applied to the relay PC for the energization of the line circuit at the beginning of the conditioning period in a manner which will herein-after be pointed out when considering the polarity selection of the impulses to be applied to the line circuit.

The picking up of relay 5CD causes the release of relay 5NCH which is sufficiently slow in dropping away to insure the establishment of a stick circuit for relay 5CD.

The means heretofore described for the initiation of the system in accordance with the depression of the entrance button 5NB is to be considered typical of the initiation provided but not shown and described in detail for the entrance points at each of the signals 6, 7, 8 and 9 (see Figs. 6A and 6B). The initiation of the system in accordance with the designation of signal 4 as an entrance point is effected in a much similar manner, except that an operator can select by the distinctive position to which he actuates the button 4NB as to whether the route established having an entrance point at signal 4 is to be automatically restored in the field upon the acceptance of the entering signal to that route by an approaching train or whether a call-on indication is to be provided for that entering signal without providing the stick feature used when the call-on signal is not designated.

If an operator depresses button 4NB (see Fig. 2A) at a time when the normal conditions of the system exist as they have been described, relay 4NR is picked up, and its energization causes the picking up of relay 4NCH which in turn causes the initiation of the system in a manner similar to that which has been described responsive to the depression of button 5NB.

The depression of button 4NB causes the picking up of relay 4NR by the energization of a circuit closed from (+), through a circuit including contact 82 of button 4NB closed in a normal position with respect to rotation of the button, contact 83 of button 4NB closed with that button in a depressed position, upper winding of relay 4NR and back contact 81 of relay CNR, to (-). The picking up of relay 4NR causes the establishment of a stick circuit for that relay similar to the circuit which has been described for relay 5NR, and also causes the picking up of relay 4NCH for the initiation of a cycle by the energization of a circuit closed from (+), through a circuit including contact 82 of button 4NB in a

normal position with respect to rotation, contact 83 of button 4NB closed in a depressed position, front contact 66 of relay 4NR, winding of relay 4NCH, wire 38, and front contact 39 of relay XCHP, to (-). The picking up of relay 4NCH causes the initiation of a cycle in a manner similar to that described in connection with the picking up of relay 5NCH.

If, however, an operator desires to designate an entrance point at signal 4C in such a manner as to cause the clearing of call-on signal 4C (see Fig. 6A), he rotates the button 4NB (see Fig. 2A) in a counterclockwise direction to an operating position, rather than depressing the button, and such rotation closes contact 64 of button 4NB which establishes a pick-up circuit for relay 4NCH, closed from (+), through a circuit including contact 64 of button 4NB in a counterclockwise operating position, back contact 65 of relay 4NCR, back contact 66 of relay 4NR, upper winding of relay 4NCH, wire 38, and front contact 39 of relay XCHP, to (-).

Upon the picking up of relay 4NCH, a circuit is closed to cause the picking up of relay 4CNR, from (+), through a circuit including contact 64 of button 4NB in a counterclockwise operating position, front contact 67 of relay 4NCH, back contact 68 of relay 4NR, and winding of relay 4CNR, to (-). When relay 4CNR is picked up a stick circuit is closed for that relay from (+), through a circuit including contact 64 of button 4NB in a clockwise operating position, front contact 69 of relay 4CNR, and winding of relay 4CNR, to (-). Such stick circuit provides for the continued energization of relay 4CNR during the dropping away of relay 4NCH, which is effected upon the picking up of relay 4CD at the start of a control cycle in a manner similar to that described for the relay 5NCH. After relay 4NCH is dropped away, a second stick circuit is closed for relay 4CNR for the purpose of maintaining that relay energized until another control has been designated by an operator to cause the picking up of relay 4NCH, from (+), through a circuit including front contact 72 of relay 4CNR, back contacts 67 of relay 4NCH, back contacts 68 of relay 4NR, and winding of relay 4CNR, to (-). The maintaining of relay 4CNR energized in such manner is essential to the transmission of a code for the restoration of a route established having its entrance point at signal 4 for the clearing of the call-on signal 4C as will hereinafter be pointed out in detail. Thus, the relay 4CNR is picked up when an operator rotates the button 4NB in a counter clockwise direction to an operating position, and that relay is maintained energized until the relay 4NCH is picked up in accordance with the designation of another control to be transmitted to the field station.

The picking up of relay 4CNR opens the pick-up circuit just described for relay 4NCH at back contact 65 to prevent the subsequent energization of relay 4NCH except after the button 4NB is restored to its normal position with respect to rotation.

Having thus described how an operator can initiate the system for the transmission of a control code appertaining to a designated entrance point, consideration will now be given to the means for initiating the transmission of a control code for defining an exit point for a route in accordance with the designation of such a control by an operator upon the depression of an exit button XB. Thus, for example, assume that an operator wishes to designate an exit point for a

route to be established at signal 5, after having designated an entrance point for that route by the depression of an entrance button such as button 7NB. To designate the exit point at signal 5 an operator depresses button 5XB, and the depression of that button causes the picking up of relay 5XCH (see Fig. 2B) by the energization of a circuit closed from (+), through a circuit including contact 73 of button 5XB closed in a depressed position, upper winding of relay 5XCH, wire 38, and front contact 38 of relay XCHP, to (-). The picking up of relay 5XCH causes the dropping away of relay XCHP by the opening of the normally energized circuit for that relay at back contact 24. Relay XCHP is sufficiently slow in dropping away to insure the establishment of a stick circuit for relay 5XCH before opening the pick-up circuit just described, closed from (+), through a circuit including back contact 74 of relay 5XCD, front contact 75 of relay 5XCH, lower winding of relay 5XCH, wire 42, and normally closed contact 43 of cancel button CAN, to (-).

The dropping away of relay XCHP upon the picking up of relay 5XCH opens the pick-up circuit for each of the change relays NCH and XCH to prevent the interfering with the transmission of a route designated if an operator should attempt to designate a second route before the first route control codes have been transmitted. And furthermore, the dropping away of relay XCHP causes the illumination of the indicator lamp XCHE to inform the operator that the ends of a route have been designated and such controls have not yet been transmitted. The indicator lamp XCHE is energized by an obvious circuit closed at back contact 39 of relay XCHP. Relay XCHP is picked up again when relay 5XCH is dropped away during the transmission of a control for that exit point and the lamp XCHE is extinguished at that time.

The picking up of relay 5XCH causes the picking up of relay CHP by the energization of a circuit closed from (+), through a circuit including back contact 44 of relay SA, back contact 45 of relay FC, upper winding of relay CHP, wire 46, and front contact 76 of relay 5XCH, to (-). Inasmuch as relay SA is picked up during each cycle of operation, and relay CHP picks up through a back contact 44 of relay SA, the picking up of relay CHP can become effective only during a period of rest or at the end of a cycle. When relay CHP is picked up, relay C is picked up by the energization of a circuit which has been described, and the picking up of that relay causes the picking up of relay 5XCD, if there is no other CD relay energized, by the energization of a circuit closed from (+), through a circuit including back contact 48 of relay LV, back contact 55 of relay 2SA, front contact 56 of relay C, back contact 57 of relay CDS, wire 58, back contact 59 of relay 5NCH, back contact 77 of relay 4NCH, a back contact of the NCH relay (not shown but represented by X) for each other entrance point, wire 78, front contact 79 of relay 5XCH, lower winding of relay 5XCD, wire 42, and normally closed contact 43 of cancel button CAN, to (-). The picking up of relay 5XCD causes the picking up of relay CDS and the establishment of a stick circuit for relay 5XCD by the energization of a circuit closed from (+), through a circuit including front contact 60 of relay CHP (see Fig. 2C), winding of relay CDS, wire 61, front contact 60 of relay 5XCD, upper winding of relay 5XCD, wire 42, and normally closed contact 43 of cancel but-

ton CAN, to (-). The picking up of relay 5XCD causes the picking up of relay PC for the initial energization of the line circuit at the beginning of the conditioning period in a manner which will be hereinafter described.

After having described how the initiation of the system is effected in accordance with the designation by an operator of typical entrance and exit points, it is believed that it will be readily apparent that the circuits provided for the initiation of the system for transmission of controls designated for each entrance and exit point are provided in accordance with the typical circuits which have just been described.

As has heretofore been pointed out in a general manner, the relays CD and XCD are energized during the initiation of a cycle of operation in accordance with the designation of a control for that respective point, and the picking up of one relay CD or XCD causes the picking up of the relay CDS which, upon opening back contact 57, opens the pick-up circuits for all of the other CD relays and maintains such circuits open throughout the cycle of operation for which one particular CD relay has been energized. Thus, such an arrangement of circuits provides that only one relay CD can be energized during one control cycle or at any one time. The circuits for the relays CD and XCD are also provided in such a manner that some relays CD and XCD have superiority over other relays of similar character where a plurality of NCH and XCH relays are energized at the same time for storing designated changes for the initiation of the transmission of a plurality of different controls. That is, for example, the picking up of relay 5NCH can cause the picking up of relay 5CD in a manner which has been described, and, relay 5XCD can be picked up in a manner which has been described when relay 5XCH is picked up; but the picking up of relay 5XCD is dependent upon the closure of back contact 71 of relay 4NCH and the back contact of each of the other NCH relays not shown. Therefore, if the relays 5NCH and 5XCH are both energized simultaneously, the picking up of relay 5NCH prevents the picking up of relay 5XCD by the opening of back contact 59, and it closes the pick-up circuit for relay 5CD at front contact 59, thus providing that relay 5CD is energized in preference to relay 5XCD under such conditions. It is believed that it will be readily apparent from the examination of the circuits for the relays CD as they have been described, that the superiority of one relay CD or XCD over the other is dependent upon the organization of the circuit network for the control of the pick-up circuits for the relays CD which provides that each relay CD or XCD having its NCH or XCH relay picked up is energized in preference to the relay CD or XCD on the right which also has its NCH or XCH relay energized.

In accordance with this general principle by which the superiority of the relays CD and XCD vary from left to right, it is provided that all of the relays CD for the initiation of the system for the transmission of designated entrance points are superior to all of the relays XCD for the initiation of the system in accordance with the designation of controls for exit points, because such CD relays are all on the left with respect to all XCD relays. The purpose for such superiority is obviously to provide that the control for a designated entrance point is always transmitted during a cycle of operation preced-

ing the designation for an exit point. Such mode of operation is provided in accordance with the general principles of entrance-exit type control systems, namely, that the entrance point shall be designated first, and the designation of an exit point subsequent to the designation of an entrance point causes a route to be established in accordance with preselecting means which is responsive to the designation of the entrance point for that route.

If an operator wishes to restore a signal to stop, or restore an entrance relay in the field which has been picked up in response to the designation of an entrance point for a particular signal, he may do so, if the entrance button NB is in a normal position with respect to rotation, by pulling the button out for that signal location, thus causing the energization of the relay NCH for that entrance point to initiate the control cycle for the transmission of the controls thus designated.

To consider more specifically how the initiation of the system is effected under such conditions, assume that an operator desires to cause the transmission of a stop code for the signal 5 at a time when the normal conditions of the system exist as they have been described. The pulling out of button 5NB causes the picking up of relay 5NCH by the energization of a circuit closed from (+), through a circuit including contact 36 of button 5NB in a pulled out position, lower winding of relay 5NCH, wire 42, and contact 43 of cancel button CAN closed in a normal position, to (-). The picking up of relay 5NCH causes the picking up of relays CHP, C, 5CD and CDS for the initiation of a control cycle by the energization of circuits similar to those which have heretofore been described.

It will be noted that initiation of a cycle for restoration is distinctive from initiation of a cycle for defining an entrance point in that the entrance relay NR for that point remains in a dropped away position to select a restoration code as is hereinafter pointed out.

Thus, in a similar manner, initiation can be effective for the transmission of a stop code for signal 4, and for each of the other signals included in the track layout.

If an operator has designated an entrance point by the designation of a call-on signal upon the rotation of the entrance button from its normal position, such as the rotation of the button 4NB in a counterclockwise direction to an operating position, the restoration of such a call-on signal to stop can be effective responsive to the restoration of such entrance button from its rotated operating position to its normal position with respect to rotation. Thus, if an operator restores by rotation the button 4NB to its normal position from a counterclockwise rotated position, the restoration of that button causes the energization of the relay 4NCH which in turn initiates the transmission of a control cycle in a manner which has been described. The picking up of relay 4NCH is effected while relay 4NCR is still energized, such relay 4NCR being maintained energized because of its stick circuit including front contact 72 of relay 4NCR. Upon the picking up of relay 4NCH, however, relay 4NCR is dropped away to open the pick-up circuit for the relay 4NCH and prevent further energization of that relay until designation by an operator of other controls to be transmitted associated with that particular signal location.

To consider more specifically the initiation of

134

the system as just described in a general manner, assume that an operator restores the button 4NB to its normal position with respect to rotation from a counterclockwise operated position. When the button has reached such normal condition the closing of contact 82 of button 4NB causes the picking up of relay 4NCH by the energization of a circuit closed from (+), through a circuit including contact 82 of button 4NB, contact 83 of button 4NB closed in its normal position, front contact 127 of relay 4CNR, lower winding of relay 4NCH, wire 42, and normally closed contact 43 of cancel button CAN, to (-). The picking up of relay 4NCH establishes a stick circuit for that relay similar to the stick circuit described for relay 5NCH, and the picking up of that relay also opens a stick circuit for relay 4CNR at back contact 67. Relay 4CNR drops away under such conditions because the other stick circuit for that relay including front contact 69 has already been opened by the rotation of the button 4NB at contact 64. Upon consideration of the stick circuits which have been described for relay 4CNR it will be apparent that the relay 4CNR has its stick circuit closed including front contact 72 until the relay 4NCH is picked up upon the restoration of the button 4NB to its full normal position, thus providing that the initiation of the system for the transmission of a stop or restoration code is effective only after the button 4NB has been completely restored to its normal position. Upon the dropping away of relay 4CNR, the pick-up circuit just described for relay 4NCH is opened at front contact 65 to prevent further picking up of the relay 4NCH until another control for the entrance point at signal 4 or signal 4C has been designated. The picking up of relay 4NCH causes the picking up of relays CHP, C, 4CD and CDS for the initiation of a control cycle by the energization of circuits in the same manner to that which has already been described.

In addition to providing a means by which an operator can establish a route in accordance with the designation of entrance and exit points, it is provided that, by operation of a lever SML provided for each track switch, an operator can cause the positioning of that track switch without establishing a route and clearing a signal. Such operation is often desirable in order to attempt to free a track switch of obstructions such as snow and ice, and is also desirable to provide a means for establishing routes which cannot be provided by the system in accordance with entrance and exit designation.

As a typical illustration of how the circuits are provided at the control office for the initiation of the system for the transmission of controls in accordance with the actuation of a lever SML, the circuits are shown and will be herein-after described in detail for the lever 2SML (see Fig. 2B) associated with track switch 2TS (see Fig. 6A). The relay 2CH associated with that lever is normally energized by a circuit which has been described, and the lever 2SML is normally in its neutral position from which it can be operated by an operator to an upper reverse position or to a lower normal position.

To consider how the initiation of the system is effected upon actuation of the lever 2SML to a reverse upper position, assume that an operator, under normal conditions, actuates the lever 2SML to such a position. Such actuation causes the picking up of relay 2CHP by the energization of a circuit closed from (+), through a circuit in-

cluding contact 84 of lever 2SML (see Fig. 2C) in an upper position, front contact 85 of relay 2CH, and winding of relay 2CHP, to (-). The picking up of relay 2CHP closes a stick circuit for that relay from (+), through a circuit including back contact 86 of relay 2CD, front contact 87 of relay 2CHP, and winding of relay 2CHP, to (-). Such stick circuit causes relay 2CHP to remain energized until relay 2CD is picked up during the initiation of the control cycle, after which it is dropped away by the opening of back contact 86.

The picking up of relay 2CD, however, opens back contact 22 in the stick circuit of relay 2CH to cause relay 2CH to drop away, and the dropping away of relay 2CH opens the pick-up circuit for relay 2CHP at front contact 85, thus providing that the pick-up circuit just described for relay 2CHP cannot again be closed until relay 2CH is again picked up, and it is further provided that relay 2CH cannot be picked up until the lever 2SML is operated back to its neutral position. The picking up of relay 2CHP causes the picking up of relays CHP, C, 2CD and CDS for the initiation of a control cycle for the transmission of controls selected in accordance with the positioning of the lever 2SML. Inasmuch as relay 2CHP can be picked up only when the lever 2SML is actuated to a full normal or reverse operating position, and the initiation of the system can become effective only when the relay 2CHP is picked up, it is believed that it will be apparent that the lever 2SML must be operated to its full normal or full reverse position before the initiation of the system for the transmission of controls becomes effective.

It is believed apparent from the circuits just described that the actuation of the lever 2SML to a normal downward position would effect the initiation of the system in a similar manner inasmuch as contact 84 is effective for causing the energization of relay 2CHP when lever 2SML is in either an upper or a lower position.

The track switch in the field positioned by an auxiliary switch control lever SML is maintained in that position until the reception of a restoration code designated by an operator by the actuation of that SML lever to its neutral position. Thus, for example, the track switch 2TS operated to a reverse position in accordance with the positioning of lever 2SML is maintained in that position until a restoration control is received in accordance with an operator actuating the auxiliary lever 2SML to its neutral position.

To consider how a control cycle is initiated responsive to the restoration of an auxiliary lever to its center neutral position, assume that an operator restores the lever 2SML from its upper reverse position to its neutral position, after controls have been transmitted to the field in accordance with the reverse position of that lever. The actuation of the lever 2SML to its neutral position from its upper reverse position causes the picking up of relay 2CHP for the initiation of the control cycle by the energization of a circuit closed from (+), through a circuit including contact 84 of lever 2SML in a neutral position, back contact 85 of relay 2CH, and winding of relay 2CHP, to (-). The picking up of relay 2CHP closes the initiation of the system for the transmission of a control cycle.

Upon the picking up of relay 2CHP, under such conditions, a pick-up circuit is closed for relay 2CH from (+), through a circuit including contact 84 of lever 2SML in a neutral position, front

contact 88 of relay 2CHP, and upper winding of relay 2CH, to (-). Upon the picking up of relay 2CH a stick circuit is closed for that relay from (+), through a circuit including contact 84 of lever 2SML in a neutral position, front contact 89 of relay 2CH, and upper winding of relay 2CH, to (-). The picking up of relay 2CH opens the pick-up circuit just described for relay 2CHP at back contact 85 to prevent the picking up of that relay again until the lever 2SML is operated to another position.

It is believed from the typical examples heretofore pointed out that it will be readily apparent to those familiar with the art how the initiation of the system is effected responsive to the designation of any entrance or exit point for any route, responsive to the restoration designation for any particular entrance point, and responsive to the positioning of any auxiliary switch control lever.

Upon considering the typical examples heretofore described of different means of initiating the system for the transmission of controls, it will be noted that the designation of an exit point for a route renders the subsequent designation of entrance and exit points ineffective until the previously designated exit control is transmitted, because the pick-up circuits for the control of the relays associated with initiation for such points is opened by the dropping away of the exit repeater relay XCHP at front contact 39; however, the designation of a restoration control for an entrance point or the condition of a track switch in accordance with the positioning of a lever SML is effective for causing the transmission of such controls irrespective of the relay XCHP. Furthermore, it is provided that an operator may designate simultaneously as many switch controls as he desires to be transmitted, and those controls will be transmitted in turn, dependent upon the position of the CD relays in their control circuits, one control cycle being transmitted for each track switch because a separate control station and a separate CD relay is provided for each track switch.

Polarity selection of stepping impulses.—The entire composite code transmitted during a control cycle, as has already been pointed out in a general manner, is made up in three different parts, each part including a code message for a different purpose. The first part of the composite code is for the purpose of field station selection; the second part is for control station selection; and the third part is for the purpose of defining the controls designated by an operator.

The first part of the composite code (for field station selection) is made up of a sufficient number of impulses to provide a different code for each field station included in the system, and in addition a "phantom" code for use during an indication cycle. The maximum number of different codes that can be provided for a particular number of impulses is equal to two raised to the power of the number of impulses.

The second part of the composite code (for control station selection) is made up of a sufficient number of impulses to provide a different code for each control station at the field station having the greatest number of control stations.

The third part of the composite code (for defining controls designated at the control office) is made up of a sufficient number of impulses to provide a different code for each different type of control to be transmitted for any one control

station. Thus, for example, each signal requires an entrance code, an exit code, and a stop or restoration code, and therefore requires the use of two impulses. If, in addition to the three controls required for each signal, a call-on signal control is provided, as is the case of signal 5 in the present disclosure, the total number of different control codes amounts to 4, which can still be provided by two impulses. Three different control codes are required for the control station for each track switch, one code being provided for operation of that track switch to a normal position in accordance with the positioning of an auxiliary lever SML at the control office, another for operation of that track switch to a reverse position in accordance with the positioning of an auxiliary lever SML at the control office, and a third code for the release of a track switch from a normal or reverse position in which it has been maintained because of its lever SML being in a corresponding position.

The following code chart shows typical codes used in this embodiment of the present invention, and illustrates in a typical manner the general composition of each composite code. The first three impulses of a composite code, including the impulse during the conditioning period, are used for field station selection; the next three impulses are used for control station selection; and the last two impulses are used for defining the controls designated by an operator.

TYPICAL CODE CHART

Impulse numbers

Code number	Field station code			Control station code			Control code		Use
	1	2	3	4	5	6	7	8	
1	+	+	-	+	+	+	+	+	5 entrance.
2	+	+	-	+	+	+	+	-	5 exit.
3	+	+	-	+	+	+	-	-	5 restore.
4	+	+	-	+	+	-	+	+	4 entrance.
5	+	+	-	+	+	-	+	-	4 exit.
6	+	+	-	+	+	-	-	+	4 call-on.
7	+	+	-	+	+	-	-	-	4 restore.
8	+	+	-	+	+	-	+	+	2 normal.
9	+	+	-	+	-	+	+	-	2 reverse.
10	+	+	-	+	-	+	-	-	2 restore.

Inasmuch as the control apparatus and circuits for one field station are typical of those provided for each field station, it is believed to be readily apparent to those familiar with the art how the system is expanded to include as many field stations as are required in practice from the typical circuits illustrated and described in this disclosure. Thus, only one field station is illustrated, and such field station is responsive to the field station code (+) (+) (-) which is determined at the control office by the predetermined connections for the first three channels of a control cycle to the buses for the control of the PC and NC relays.

As a specific example of the means provided for the determining of the polarity of each impulse during a cycle of operation, assume that an operator has designated an entrance point at signal 5 by the depression of button 5NB (see Fig. 2A), and that the system has been initiated for the transmission of the controls designated, thus causing the energization of the code determining relay 5CD and of the control cycle relay C (see Fig. 2C). Upon the picking up of relay 5CD, a circuit is closed for the energization of relay PC for causing the line circuit to be energized with positive polarity, from (+), through

a circuit including front contact 90 of relay C (see Fig. 2C), back contacts 91, 92, 93, 94, 95, 96 and 97 of relays 7V, 6V, 5V, 4V, 3V, 2V and 1V respectively, wire 98, front contact 99 of relay 5CD, wire 100, and winding of relay PC, to (-). The picking up of relay PC causes the picking up successively of relays F, FP, 2FP, SA and 2SA. The picking up of relay 2FP causes the picking up of the half-step relay VP, and the picking up of relay VP causes the picking up of relays E and EP respectively. The picking up of relay EP causes the deenergization of the line circuit by opening back contact 101 (see Fig. 3) to mark the end of the conditioning period and the beginning of the first "off" period.

Upon the deenergization of the line circuit at the beginning of the first "off" period, relays F, FP and 2FP are successively dropped away. The dropping away of relay 2FP causes the picking up of the first stepping relay 1V, and the picking up of that relay causes relays E and EP to be successively deenergized.

The picking up of relay 1V opens the circuit previously described for relay PC at back contact 97 (see Fig. 2C) and the closing of front contact 97 causes the energization of relay PC by another circuit closed from (+), through a circuit including front contact 90 of relay C, back contacts 91, 92, 93, 94, 95 and 96 of relays 7V, 6V, 5V, 4V, 3V and 2V, respectively, front contact 97 of relay 1V, wire 102, front contact 103 of relay 5CD, wire 100, and winding of relay PC, to (-).

The dropping away of the relay EP marks the end of the first "off" period and closes the line circuit at back contact 101 to cause its energization with positive polarity in accordance with the relay PC energized. In accordance with such energization the relays F, FP and 2FP respond, and the picking up of relay 2FP causes the dropping away of relay VP, and the dropping away of that relay causes the energization of the relays E and EP to mark the end of the first "on" period and the beginning of the second "off" period.

During the second "off" period the second stepping relay 2V is picked up, and the picking up of that relay opens the circuit previously described for relay PC at back contact 96 and closes a circuit for the relay NC, because the third character of the code is to be (-), from (+), through a circuit including front contact 90 of relay C, back contacts 91, 92, 93, 94 and 95 of relays 7V, 6V, 5V, 4V and 3V respectively, front contact 96 of relay 2V, wire 104, front contact 105 of relay 5CD, wire 106, and winding of relay NC, to (-). Upon the closing of the line circuit at the end of the second "on" period by the dropping away of relay EP, the line circuit becomes energized with negative polarity in accordance with the energization of relay NC.

During the third "off" period the circuit for relay NC is opened at back contact 95 of relay 3V, and the closing of front contact 95 causes the energization of relay PC by a circuit closed from (+), through a circuit including front contact 90 of relay C, back contacts 91, 92, 93 and 94 of relays 7V, 6V, 5V and 4V respectively, front contact 95 of relay 3V, wire 107, front contact 108 of relay 5CD, wire 100, and winding of relay PC, to (-). The picking up of relay PC due to such energization causes the next impulse to be (+).

During the fourth "off" period, relay 4V is picked up, and the picking up of that relay opens the circuit just described for relay PC at back contact 94 and closes another circuit for that

relay at front contact 94, from (+), through a circuit including front contact 90 of relay C, back contacts 91, 92 and 93 of relays 7V, 6V and 5V respectively, front contact 94 of relay 4V, wire 109, front contact 110 of relay 5CD, wire 100, and winding of relay PC, to (-). The picking up of relay PC causes the next impulse applied to the line circuit to be (+).

During the fifth "off" period relay 5V is picked up, and the picking up of that relay opens the circuit just described for relay PC at back contact 93 and closes another circuit for that relay from (+), through a circuit including front contact 90 of relay C, back contacts 91 and 92 of relays 7V and 6V respectively, front contact 93 of relay 5V, wire 111, front contact 112 of relay 5CD, wire 100, and winding of relay PC, to (-). The picking up of relay PC causes the next impulse of the line circuit to be (+).

During the sixth "off" period the relay 6V is picked up, and the picking up of that relay opens the circuit just described for relay PC at back contact 92, and closes another circuit for relay PC from (+), through a circuit including front contact 90 of relay C, back contact 91 of relay 1V, front contact 92 of relay 6V, wire 113, front contact 114 of relay 5CD, front contact 115 of relay 5NR, wire 100, and relay PC, to (-). The picking up of relay PC, due to the energization of that circuit, causes the next impulse of the line circuit to be (+).

During the seventh "off" period relay 7V is picked up, and the picking up of that relay opens the circuit just described for relay PC and closes another circuit for that relay from (+), through a circuit including front contact 90 of relay C, front contact 91 of relay 1V, wire 116, front contact 117 of relay 5CD, front contact 118 of relay 5NR, wire 100, and winding of relay PC, to (-). The picking up of relay PC due to the energization of the circuit just described causes the last impulse of the control cycle to be (+).

The relay VP shifts in its position during each "on" period throughout the cycle. Thus, in view of the fact that the VP relay is picked up during the conditioning period and is dropped out during the second impulse, the general rule can be applied that the relay VP picks up during each odd numbered impulse and is dropped away during each even numbered impulse.

Inasmuch as the last impulse is of an even number the relay VP is dropped away during that impulse and the dropping away of that relay causes the relay E to be picked up, and that relay in picking up causes the picking up of the relay EP to open the line circuit and mark the beginning of the clearing out period. The dropping away of relay VP also causes the picking up of relay LV, and that relay, when picked up, is maintained energized until the slow acting relay 2SA is dropped away at the end of the clearing out period.

During the clearing out period the relays F, FP, 2FP, SA and 2SA are successively dropped away because of the de-energization of the line circuit. The dropping away of relay SA causes the dropping away of the stepping relays which have been energized, with the exception of the last step relay LV, and the dropping away of relay 2SA causes the dropping away of relay LV and the impulsive relays E and EP. The relay CHP is dropped away upon the opening of its stick circuit at back contact 48 (see Fig. 2C) when relay LV is picked up if contact 50 of relay EP connected in multiple with contact 48 of relay LV is

open, and the dropping away of relay CHP causes the dropping away of relays 5CD and CDS because of the opening of the circuit for those relays at front contact 60. Upon the dropping away of relay 5CD the stick circuit for relay 5NR is opened at front contact 40 (see Fig. 2A) to cause relay 5NR to be dropped away and thus complete the restoration of the relays at the control office to their normal-at-rest positions.

The code thus selected for the control cycle corresponds to code No. 1 in the above code chart and is for the defining of an entrance point for a route at signal 5. If, however, an operator designates a restoration control to be transmitted for the entrance point at signal 5 by the pulling out of button 5NB, relay 5CD is picked up upon initiation of the cycle and a field station code and a control station code corresponding with the codes just described is transmitted. The control code varies, however, from the code described above because it is selected with relay 5NR de-energized as that relay is not picked up when button 5NB is pulled out from its normal position. The code for the entire cycle for restoration at signal 5 therefore corresponds to code No. 3 of the above code chart.

The seventh impulse is (—) when a restoration code has been designated for transmission for the entrance point at signal 5 because relay NC is picked up during the sixth "off" period by the energization of a circuit closed from (+), through a circuit including front contact 90 of relay C (see Fig. 2C), back contact 91 of relay 7V, front contact 92 of relay 6V, wire 113, front contact 114 of relay 5CD, back contact 115 of relay 5NB, wire 106, and winding of relay NC, to (—).

The eighth impulse is (—) when a restoration control has been designated for transmission for the entrance point at signal 5 because relay NC is picked up during the seventh "off" period by the energization of a circuit closed from (+), through a circuit including front contact 90 of relay C, front contact 91 of relay 7V, wire 116, front contact 117 of relay 5CD, back contact 118 of relay 5NR, wire 106, and winding of relay NC, to (—).

If an operator initiates the transmission of controls by the designation of an exit point at signal 5 upon the depression of button 5XB, the relay 5XCD is picked up, and the picking up of that relay selects for transmission code impulses corresponding to code No. 2 of the above code chart. Inasmuch as the field station code and the control station code for that control cycle are identical to the code as selected by relay 5CD in the above description it is believed unnecessary to describe the selection of such code in detail as the circuits providing such selection are provided in a manner similar to circuits which have been described.

The seventh impulse is (+), when an exit control has been designated for transmission for the exit point at signal 5, because relay PC is picked up during the sixth "off" period by the energization of a circuit closed from (+), through a circuit including front contact 90 of relay C (see Fig. 2C), back contact 91 of relay 7V, front contact 92 of relay 6V, wire 113, front contact 119 of relay 5XCD, wire 100, and winding of relay PC, to (—).

The eighth impulse is (—) when an exit control has been designated for transmission for the exit point at signal 5, because relay NC is picked up during the seventh "off" period by the energization of a circuit closed from (+),

through a circuit including front contact 90 of relay C, front contact 91 of relay 7V, wire 116, front contact 120 of relay 5XCD, wire 106, and winding of relay NC, to (—).

If an operator designates a control for a different control station, such as control station No. 2 (see Fig. 1), for signal 4, the same field station code is selected as has been described, but a different control station code is selected by the picking up of relay 4CD, which is associated with the transmission of entrance and restoration codes, or by the picking up of relay 4XCD which is associated with the transmission of an exit control code for the exit point at signal 4. The part of the composite code for a cycle for station 2 relative to the selection of that station is therefore (+)(+)(—) and is therefore distinguished from the control station code (+)(+)(+) as has been described for control station No. 1 associated with signal 5.

As an example of the selection of codes for a different control station from the one which has heretofore been described, consider that an operator depresses the button 4NB and causes the initiation of the system for the transmission of controls for defining an entrance point for a route at signal 4. The depression of button 4NB causes the energization of relay 4NR, but relay 4CNR is maintained in a dropped away position because that relay is picked up only when a call-on control is designated. The picking up of relay 4CD during the initiation of the cycle causes the impulses (+)(+)(—)(+)(+) to be applied to the line circuit in their respective order by the energization of circuits similar to those which have been described as being selected by relay 5CD, and the picking up of relay 5V during the fifth "off" period opens the circuit for relay PC which was energized for the previous impulse at back contact 93 and causes the energization of relay NC by a circuit closed from (+), through a circuit including front contact 90 of relay C, back contacts 91 and 92 of relays 7V and 6V respectively, front contact 93 of relay 5V, wire 111, front contact 121 of relay 4CD, wire 106, and winding of relay NC, to (—). The picking up of relay NC causes the sixth impulse to be (—).

The picking up of relay 6V during the sixth "off" period opens the circuit just described for relay NC and causes the picking up of relay PC by the energization of a circuit closed from (+), through a circuit including front contact 90 of relay C, back contact 91 of relay 7V, front contact 92 of relay 6V, wire 113, front contact 122 of relay 4CD, front contact 123 of relay 4NR, wire 100, and winding of relay PC, to (—). The picking up of relay PC due to such energization causes the seventh impulse of the control cycle to be (+).

The picking up of relay 7V during the seventh "off" period opens the circuit just described for relay PC at back contact 91 and closes another circuit for that relay from (+), through a circuit including front contact 90 of relay C, front contact 91 of relay 7V, wire 116, front contact 124 of relay 4CD, front contact 125 of relay 4NR, wire 100, and winding of relay PC, to (—). The picking up of relay PC due to such energization causes the eighth impulse of the line circuit to be (+). Thus, the selection of a code for transmission is completed in accordance with code No. 4, of the code chart.

If an operator designates an entrance point at signal 4 and the clearing of a call-on signal 4C

by the rotation of button 4NB in a counter-clockwise direction, the relay 4CNR is energized, and relay 4NR remains deenergized in accordance with circuits which have already been described. The picking up of relay 4CD during the initiation of a control cycle for the transmission of controls thus designated causes the selection of polarities for the field station and control station codes in the manner corresponding to that which has been described. The seventh impulse is (-), when a call-on control has been designated for signal 4C, because relay NC is picked up during the sixth "off" period by the energization of a circuit closed from (+), through a circuit including front contact 90 of relay C, back contact 91 of relay 7V, front contact 92 of relay 6V, wire 113, front contact 122 of relay 4CD, back contact 123 of relay 4NR, wire 106, and winding of relay NC, to (-).

The eighth impulse is (+) if a control has been designated for an entrance point and the clearing of call-on signal 4C, because relay NC is dropped away by the opening of back contact 91 during the seventh "off" period when relay 7V is picked up, and the picking up of relay 7V closes a circuit for the energization of relay PC from (+), through a circuit including front contact 90 of relay C, front contact 91 of relay 7V, wire 116, front contact 124 of relay 4CD, back contact 125 of relay 4NR, front contact 126 of relay 4CNR, wire 100, and winding of relay PC, to (-). Thus, the code is completely selected for a control cycle for the designation of a call-on signal in accordance with the actuation of button 4NB to a counterclockwise rotated position, such code corresponding with code No. 6 in the above code chart.

If a control cycle has been initiated by the designation for restoration at signal 4 or signal 4C, relays 4NR and 4CNR are deenergized during the cycle to select the control code (-)(-) for the last two impulses of the cycle corresponding with code No. 7 in the above code chart.

The seventh impulse is (-) when a restoration control has been designated by the actuation of button 4NB because relay NC is picked up during the sixth "off" period by the energization of a circuit which has been described.

The eighth impulse is (-) when a restoration control has been designated by the actuation of button 4NB because relay NC is picked up during the seventh "off" period by the energization of a circuit closed from (+), through a circuit including front contact 90 of relay C, front contact 91 of relay 7V, wire 116, front contact 124 of relay 4CD, back contact 125 of relay 4NR, back contact 126 of relay 4CNR, wire 106, and winding of relay NC, to (-).

It is believed from the typical circuits heretofore described, that it will be readily apparent to those familiar with the art how the code elements have their polarities selected to correspond with the codes in the typical code chart, and how such typical circuits can be applied to the control of any track layout encountered in practice.

Field station reception of codes.—Each field station has a bank of stepping relays which, as long as the transmission of code elements corresponds to the predetermined code for selection of that field station, respond in synchronism with the stepping relays V of a similar stepping bank at the control office. In other words, as long as the code elements transmitted correspond with the field station code assigned to each field station, the stepping relays at that field station re-

spond, one during each "off" period and they are maintained energized until the end of the cycle. As soon as the stepping fails at any field station because of the code transmitted being out of correspondence with that field station code, such field station becomes ineffective for reception of controls during that cycle because of failure to complete the stepping. Thus, at the end of the field station selection code, only the one field station responsive to such code is responsive to the remaining code elements during that cycle. Such mode of operation is provided by the relays SO and SOS (see Fig. 4) at each field station which have their circuits arranged in such a manner that the relay SO is picked up at the beginning of a control cycle, if the first element of the code corresponds with the code assigned to that field station, and such relay is maintained energized throughout the cycle to permit the stepping at that field station only as long as the code elements for field station selection applied to the line circuit at the beginning of the cycle correspond with the code assigned to that field station. The field station illustrated in Fig. 4 is selected by a field station code (+)(+)(-) because of the position of jumpers 128, 129 and 130 in the control circuit for the relays SO¹ and SOS¹.

Thus, in accordance with the general principles outlined above, the energization of the line circuit with positive potential during the conditioning period causes the energization of relay F¹ to cause its polar contacts to be operated to a right hand position, and the picking up of relay F¹ causes the picking up of its repeater relay FP¹. The positioning of the polar contacts of relay F¹ causes the picking up of the relays SO¹ and SOS¹, and the picking up of relay FP¹ causes the energization successively of relays SA¹ and SB¹. The picking up of relay SB¹ causes the picking up of relay VP¹, and the picking up of that relay completes the conditioning of the relays at that field station during the conditioning period.

Upon the deenergization of relay F¹ at the end of the first impulse, the dropping away of relay FP¹ causes the picking up of the first stepping relay 1V¹ to correspond with the picking up at the same time of relay 1V at the control office.

During the second impulse of the control cycle the relay VP shifts in its position to condition a circuit for allowing the energization of the stepping relay 2V¹ upon the dropping away of relay FP¹ during the second "off" period. Thus, the stepping is accomplished during each "off" period, and the relay VP shifts in its position during each "on" period to condition a circuit for the energization of a stepping relay during the following "off" period.

The relay SO¹ is maintained picked up by the energization of its upper winding during each period of energization of the line circuit during the transmission of the field station selecting code, and it is maintained energized by its stick circuits during each "off" period and during the remainder of the control cycle after the field station selecting code has been completely received.

It is believed from the above general description, and in view of the detailed description provided in the patent to Judge et al., Patent No. 2,082,544, dated June 1, 1937, that it will be readily understood by those familiar with the art how the field station illustrated in Fig. 4 is selected responsive to the field station code (+)(+)(-), and how the first two stepping relays 1V¹ and 2V¹ at that field station are picked up during the reception of such code.

During the impulse for each of the following elements of the code, a decoding relay PS or NS is picked up during each impulse in accordance with the polarity of that impulse, a PS relay being picked up responsive to the positive energization of the line circuit and an NS relay being picked up responsive to the negative energization of the line circuit.

In order that each PS and NS relay can be readily identified with the impulse number to which it is responsive, the reference characters PS and NS are provided with preceding numerals corresponding with the impulse number in the control code for which such PS and NS relays are provided. Thus, with reference to Figs. 5A and 5B, the relays 4PS and 4NS are associated with the fourth impulse in a code, the relays 5PS and 5NS are associated with the fifth impulse of a code, the relay 6PS and 6NS are associated with the sixth impulse of a code, the relays 7PS and 7NS are associated with the seventh impulse of a code, and the relays 8PS and 8NS are associated with the eighth impulse of a code.

As a typical example of how the relays PS and NS are energized for each step, consideration will be given in detail to the circuits provided for the energization of relay 8PS and 8NS. The positive energization of the line circuit during the eighth impulse, when the field station illustrated in Fig. 4 is selected for the reception of controls, causes the picking up of relay 8PS by the energization of a circuit closed from (+), through a circuit including front contact 210 of relay SO¹, polar contact 211 of relay F¹ in a right hand position, front contact 212 of relay 7V¹ and lower winding of relay PS, to (—). The negative energization of the line circuit during the eighth impulse, when the field station illustrated in Fig. 4 is selected for the reception of controls, causes the picking up of relay 8NS by the energization of a circuit closed from (+), through a circuit including front contact 210 of relay SO¹, polar contact 211 of relay F¹ in a left hand position, front contact 213 of relay 7V¹, and lower winding of relay 8NS, to (—).

Each PS and NS relay is maintained energized when once picked up by the energization of its upper winding with a stick circuit similar to the stick circuit for relay 4PS (see Fig. 5A) which is closed from (+), through a circuit including front contact 131 of relay SO¹, front contact 132 of relay 4PS and upper winding of relay 4PS, to (—). The energization of that circuit is prolonged during the clearing out period by energy applied thereto at front contact 133 of relay LV¹, thus maintaining the relays PS and NS energized until after the end of the execution period at the end of a cycle.

In view of the foregoing description and the detailed description provided in the above mentioned Judge et al. Patent No. 2,082,544, dated June 1, 1937, it is believed sufficient for considering the novel features of the present invention to assume that each relay PS and NS is energized responsive to the respective positive or negative energization of the line circuit for that particular impulse, and is maintained picked up until the end of the cycle. Thus, upon assuming the transmission from the control office of a control cycle in accordance with the depression of button 5NB (see Fig. 2A), the relays 4PS, 5PS, 6PS, 7PS and 8PS (see Fig. 5A) are picked up during the fourth, fifth, sixth, seventh and eighth impulses respectively of that control cycle. The picking up of relay 6PS during that control cycle completes

the decoding of the control station code (+) (+) (+) for control station No. 1 (see Fig. 1) and causes the picking up of the station relay 1ST for that station (see Fig. 5B), by the energization of a circuit closed from (+), through a circuit including back contact 134 of relay 6NS (see Fig. 5A), back contact 135 of relay 5NS, back contact 136 of relay 4NS, front contact 137 of relay 4PS, front contact 138 of relay 5PS, front contact 139 of relay 6PS, wire 140, and winding of relay 1ST, to (—). If, instead of designating an entrance control for signal 5 an operator designates a control for the exit point at signal 5, the same control station code is applied at the control office as has heretofore been described, and the energization of relay 1ST is effected because of the reception of such code.

If, on the other hand, an operator designates an entrance, exit, or restoration control for signal 4 by the actuation of button 4NB or button 4XB (see Fig. 2A) at the control office, the control cycle includes the control station code (+)(+)(—) (corresponding with code No. 4 in the above typical code chart), and, the picking up of relay 6NS during the reception of such code, the relay 2ST is picked up instead of relay 1ST by the energization of a circuit closed from (+), through a circuit including back contact 141 of relay 6PS, back contact 135 of relay 5NS, back contact 138 of relay 4NS, front contact 137 of relay 4PS, front contact 138 of relay 5PS, front contact 142 of relay 6NS, wire 143, and winding of relay 2ST, or (—).

If an operator designates a control in the control office to be transmitted in accordance with the positioning of a lever SML, that particular SML lever is identified in the code transmitted during the cycle by a control station code distinctive from the control station code used for other types of control and for other SML levers. Thus, for example, the designation of a control at the control office by the actuation of the lever 2SML (see Fig. 2B) causes the transmission of impulses during the control cycle for transmission of the controls thus designated corresponding with the control station code (+)(—)(+) as shown in the above code chart included in code Nos. 8, 9 and 10. Thus, in accordance with the reception of such code at the field station, the relays 4PS, 5NS and 6PS are picked up, and the picking up of relay 6PS during the sixth impulse causes the picking up of the station relay 3ST (provided for the control station No. 3 shown in Fig. 1) by the energization of a circuit closed from (+), through a circuit including back contact 134 of relay 6NS, back contact 164 of relay 5PS, back contact 136 of relay 4NS, front contact 137 of relay 4PS, front contact 165 of relay 5NS, front contact 166 of relay 6PS, wire 167, and winding of relay 3ST, to (—).

It is believed from the description of the circuits by which relays 1ST, 2ST and 3ST are controlled that it will be readily apparent how the ST relay for each control station illustrated diagrammatically in Fig. 1 is responsive during the reception of the sixth impulse to its particular control station code. Thus, during each control cycle, one station relay ST is picked up, and the picking up of that station relay renders the control codes received during the remainder of the cycle effective for governing the control apparatus associated with that particular control station.

When the seventh and eighth impulses of the control cycle are received at the field station

they are decoded by the decoding relays PS and NS for their respective impulses, and during the clearing out period, an execution circuit is closed for the energization of the control relays in accordance with the codes received. Such execution period is initiated upon the dropping away of the relay SA¹, which drops away as soon as a period of deenergization of the line circuit is reached, after the stepping is completed, which is longer than the time space regularly provided between impulses of a control cycle, and it is terminated by the dropping away of last step relay LV¹ at the end of the clearing out period.

To consider the reception of a control for defining an entrance point in accordance with such entrance designation, assume that an operator has caused the transmission of a control for an entrance point at signal 5 in accordance with the depression of button 5NB (see Fig. 2A), and assume that relays 7PS and 8PS are picked up (see Fig. 5A) during the seventh and eighth impulses respectively of such control cycle. The dropping away of relay SA¹ during the clearing out period following the eighth impulse causes the picking up of relay 5NR¹ in accordance with the code received by the energization of a circuit closed from (+), through a circuit including back contact 144 of relay SA¹, front contact 145 of relay LV¹, back contact 146 of relay 7NS, back contact 147 of relay 8NS, front contact 148 of relay 8PS, front contact 149 of relay 7PS, wire 150, front contact 151 of relay 1ST, and lower winding of relay 5NR¹, to (—). The picking up of relay 5NR¹ closes a stick circuit for that relay to maintain it picked up after the end of the execution period, from (+), through a circuit including front contact 152 of relay 2TR, back contact 153 of relay B, front contact 154 of relay 5NR¹, and upper winding of relay 5NR¹, to (—). Relay B is picked up only momentarily during the execution period when a restoration control is received at that field station, and thus, to prevent the restoration of relay 5NR¹ except when such control is for that control station, back contact 163 of relay 1ST is connected in multiple with back contact 153 of relay B in the stick circuit just described.

If an operator designates an exit point at signal 5 by the depression of button 5XB, the code having its last two impulses (+) and (—) respectively is received at the field station and the relays 7PS and 8NS are energized to provide during the execution period that relay 5XZ is energized by a circuit closed from (+), through a circuit including back contact 144 of relay SA¹ (see Fig. 5A), front contact 145 of relay LV¹, back contact 146 of relay 7NS, back contact 155 of relay 8PS, front contact 156 of relay 8NS, front contact 157 of relay 7PS, wire 158, front contact 159 of relay 1ST, and winding of relay 5XZ, to (—). The picking up of relay 5XZ causes the picking up of an exit relay 5XR which is maintained by a stick circuit in a manner which will be hereinafter described upon consideration of the self-selecting network system responsive to the controls received from the control office. Relay 5NR¹ cannot be energized during the reception of such a code because the circuit for that relay is open at back contact 147 of relay 8NS, and in a similar manner relay 5XZ cannot be picked up when a code is received for the energization of relay 5NR¹ because the circuit for relay 5XZ is open under such conditions at back contact 155 of relay 8PS.

If an operator designates a restoration con-

trol to be transmitted for an entrance point such as the entrance point at signal 5, the pulling out of button 5NB (see Fig. 2A) causes the transmission of a restoration control cycle, in a manner which has heretofore been described, having a code corresponding with code No. 3 of the above code chart. To correspond with the seventh and eighth impulses of that code being (—) (—) respectively, the relays 7NS and 8NS (see Fig. 5A) are energized during the reception of such code, and during the execution period the restoration relay B (see Fig. 5B) is picked up by the energization of a circuit closed from (+), through a circuit including back contact 144 of relay SA¹, front contact 145 of relay LV¹, back contact 160 of relay 7PS, back contact 155 of relay 8PS, front contact 156 of relay 8NS, front contact 161 of relay 7NS, wire 162, and winding of relay B, to (—). The picking up of relay B causes the restoration of relay 5NR¹ by the opening of the stick circuit for that relay at back contact 153 because back contact 163 of relay 1ST connected in multiple with that contact is open at that time.

If an operator designates an entrance point at signal 4 by the depression of button 4NB (see Fig. 2A) in the control office, a control cycle is transmitted for defining such entrance control by the application of the series of impulses to the line circuit corresponding with code No. 4 in the above code chart. The reception of such impulses at the field station causes the picking up of relay 2ST and by the energization of a circuit which has been described, and the relays 7PS and 8PS (see Fig. 5A) are picked up to provide that relay 4NR¹ is picked up during the execution period of that cycle of operation by the energization of a circuit closed from (+), through a circuit including back contact 144 of relay SA¹, front contact 145 of relay LV¹, back contact 146 of relay 7NS, back contact 147 of relay 8NS, front contact 148 of relay 8PS, front contact 149 of relay 7PS, wire 168, front contact 169 of relay 2ST, lower winding of relay 4NR¹, and back contact 170 of relay 4CNR¹, to (—). The picking up of that relay closes a stick circuit for its upper winding from (+), through a circuit including front contact 152 of relay 2TR, front contact 171 of relay 4NR¹, back contact 172 of relay B, front contact 173 of relay 4NR¹, and upper winding of relay 4NR¹, to (—). The picking up of relay 4NR¹ causes the initiation of the establishment of a route at an entrance point at signal 4 in a manner which will be hereinafter described in detail.

If instead of depressing the button 4NB to designate an entrance point in the control office (see Fig. 2A) an operator rotates the button 4NB in a counter clockwise direction to an operating position for the transmission of an entrance control for the call-on signal 4C, a code is transmitted corresponding to code number 6 in the above code chart, and upon the reception of that code at the field station the relay 2ST is picked up, and the relays 7NS and 8PS are picked up to correspond with the last two elements of the code received. During the execution period at the end of that cycle, relay 4CNR¹ is picked up by the energization of a circuit closed from (+), through a circuit including back contact 144 of relay SA¹ (see Fig. 5A), front contact 145 of relay LV¹, back contact 160 of relay 7PS, back contact 147 of relay 8NS, front contact 148 of relay 8PS, front contact 174 of relay 7NS, wire 175, front contact 176 of relay 2ST, back contact 177 of re-

lay 4NR¹, and lower winding of relay 4CNR¹, to (—). The picking up of relay 4CNR¹ because of the energization of that circuit closes a stick circuit for that relay from (+), through a circuit including back contact 171 of relay 4NR¹, back contact 172 of relay B, front contact 173 of relay 4CNR¹, and upper winding of relay 4CNR¹ to (—).

It will be noted from the pick-up circuits just described for relays 4NR¹ and 4CNR¹ that the two relays are electrically interlocked, so that the reception of a control code for the energization of either relay becomes effective only if the other relay is in a dropped away position to correspond with that entrance point not being included in a route which is already established. Upon consideration of the stick circuits for the relays 4NR¹ and 4CNR¹ it will be obvious that the relay 4NR¹ is maintained energized dependent for restoration upon passage of a train past that entrance point to cause the dropping away of the track relay 2TR and the opening of front contact 152, while the relay 4CNR¹ is dependent for deenergization only upon the opening of back contact 172 of relay B upon reception of a restoration code for that particular control station. Such control circuits provide that signal 4 is a "stick" signal and signal 4C is a "non-stick" signal.

If an operator designates a control for the restoration for an entrance point designated for signal 4, the designation of such control by the pulling out of button 4NB (see Fig. 2A) at the control office causes the transmission of a control cycle providing a code in accordance with code No. 7 in the above code chart. The reception of that code causes the energization of relay 2ST, and the picking up of the relays 7NS and 8NS during the seventh and eighth impulses respectively. During the execution period at the end of that control cycle relay B is picked up by the energization of a circuit which has already been described, and the picking up of that relay opens the stick circuit for relay 4NR¹ at back contact 172 and causes that relay to drop away because back contact 179 of relay 2ST connected in multiple with back contact 172 of relay B in that circuit is open at that time on account of relay 2ST being selected by the station code received. Inasmuch as only one ST relay can be energized during any one cycle, the picking up of relay B is ineffective for the restoration of any other entrance relays NR¹ that are picked up at that time because the back contact of each relay B in each stick circuit for its NR¹ relay has connected in multiple with it a back contact of the station relay ST for the particular control station with which that relay NR¹ is associated.

As has been heretofore pointed out, the rotation of the button 4NB from its counter clockwise operating position to its normal position causes the transmission of a restoration code to the field station the same as is transmitted if the button 4NB is pulled out from its normal position, and the reception of that code at the field station causes the energization of relays 2ST and B to cause the dropping away of relay 4CNR¹ if that relay is picked up, because of the opening of back contact 172 (see Fig. 5B) of relay B and back contact 179 of relay 2ST, in the stick circuit for relay 4CNR¹.

If an operator designates a control for operating the track switch 2TS to a reverse position by actuating the lever 2SML to an upper position (see Fig. 2B) a code is transmitted to the

field station corresponding to code No. 9 in the above code chart, and relay 3ST (See Fig. 5B) is picked up at the field station in accordance with the code received. The relays 7PS and 8NS are picked up in accordance with such code during the seventh and eighth impulses respectively, and relay 2R¹ is picked up during the execution period at the end of that control cycle by the energization of a circuit closed from (+), through a circuit including back contact 144 of relay SA¹ (see Fig. 5A), front contact 145 of relay LV¹, back contact 146 of relay 7NS, back contact 145 of relay 8PS, front contact 146 of relay 8NS, front contact 147 of relay 7PS, wire 148, front contact 149 of relay 3ST, and upper winding of relay 2R¹, to (—). The picking up of that relay closes a stick circuit for its lower winding from (+), through a circuit including back contact 182 of relay B, back contact 183 of relay 2N¹, front contact 184 of relay 2R¹, and lower winding of relay 2R¹, to (—). When relay 3ST is dropped away at the end of that control cycle the closing of back contact 185 of that relay applies energy to the stick circuit just described in multiple with back contact 182 of relay B. It is believed obvious from the stick circuit just described that the relay R is maintained in its picked up position until a restoration code is received to cause the release of that stick circuit (in a manner similar to that which has been described for the release of the stick circuits for the NR relays) by the picking up contemporaneously of the relays 3ST and B to open the stick circuit just described at back contacts 185 and 182 respectively. It has been pointed out that the transmission of a code to cause such restoration of the relay 2R¹ can be effected upon the actuation of the lever 2SML from its reverse position to its center neutral position, and that the code transmitted corresponds to code No. 10 of the above code chart. The reception of such a code causes the picking up of relay 3ST responsive to the control station code (+) (—) (+) by the energization of a circuit which has been described, and the reception of the control code (—) (—) causes the picking up of relay B by the energization of a circuit which has also been described.

If an operator actuates the lever 2SML from its center neutral position to a downward position for the designation of a normal position for the track switch 2TS, a code is transmitted corresponding to code No. 8 in the above code chart, and the reception of such code at the field station causes the picking up of relay 3ST, and the picking up of relays 7PS and 8PS during the seventh and eighth impulses respectively. Relay 2N¹ is picked up during the execution period by the energization of a circuit closed from (+), through a circuit including back contact 144 of relay SA¹, front contact 145 of relay LV¹, back contact 146 of relay 7NS, back contact 147 of relay 8NS, front contact 148 of relay 8PS, front contact 149 of relay 7PS, wire 148, front contact 147 of relay 3ST, and upper winding of relay 2N¹, to (—). The picking up of relay 2N¹ causes a stick circuit to be closed for the lower winding of that relay from (+), through a circuit including back contact 182 of relay B, back contact 188 of relay 2R¹, front contact 189 of relay 2N¹, and lower winding of relay 2N¹, to (—).

Having thus described several typical circuits for the reception of entrance, exit and switch controls, it is believed that it will be readily apparent to those familiar with the art how the

typical circuits which have been described can be applied to the controls for each entrance and exit point and for each track switch provided in any track layout encountered in practice, and how the circuits not shown are provided for the various entrance and exit points in this embodiment of the present invention.

Self-selecting network.—Although the present invention contemplates the use in the field of an entrance-exit type of system provided in accordance with the general principles set forth in the application of Wight and Langdon, Ser. No. 245,384, filed December 13, 1938, inasmuch as the general organization of most entrance-exit switch and signal control systems is such that they are responsive to designation of entrance and exit points, it is to be understood that a number of other entrance-exit type systems can be used in conjunction with the features of the present invention relative to the transmission of controls to the field pertinent to the defining of entrance and exit points and restoration for such points. Although a general description of the entrance-exit type of system used in this embodiment of the present invention is herein-after included, reference is to be made to the above Wight and Langdon application for a more complete disclosure of such system.

The general mode of operation of such entrance-exit system is that the designation of an entrance point for a route, as is provided in the present system by the picking up of an entrance relay NR¹ in the field, causes the pre-selection in a general manner of each available route emanating from that entrance point by the energization of a preselecting relay Y for each track switch that can be trailed in a particular predetermined position upon passage of a train over a route extending from such designated entrance point. Upon designation of an exit point, as is provided in the present invention by the momentary energization of an exit execution relay XZ, an exit relay XR is picked up if there is an available route between a designated entrance point and that exit point, and when once picked up such exit relay is maintained energized by a stick circuit dependent upon the picked up position of the entrance relay NR¹ for the entrance end of that route. The picking up of such exit relay causes the initiation of the selection of the position for each of the track switches included in a route between the entrance and exit points designated for the establishment of that route.

The position to which each track switch is to be operated is selected by the energization of a normal relay N or a reverse relay R for such track switch for causing the operation of that track switch to a corresponding position. The selective energization of the relays N and R is rendered effective upon the picking up of the exit relay XR for the exit end of a route designated. A normal or a reverse relay is energized for each track switch included in a route between the entrance and exit points designated, the energization of each switch control relay being dependent upon the selection of a route up to that track switch from the exit point designated. Each track switch that would be trailed normal if a train were to pass over a route from a designated exit point to a designated entrance point has its normal switch control relay N energized, and each track switch that would be facing upon such a train movement has its normal relay N or its reverse relay R selected in

accordance with the picked up or dropped away position of the relay Y for that track switch which is positioned responsive to the designation of the entrance end of that route.

5 To consider as a typical example how a route is selected in accordance with entrance and exit designation, with reference to Figs. 6A and 6B, assume that an operator has designated an entrance point at signal 4 by the depression of button 4NB at the control office (see Fig. 2A) and that such entrance designation has caused the picking up of the entrance relay 4NR¹ in the field in a manner which has been described.

10 The picking up of relay 4NR¹ in the field causes the picking up of the preselecting relay 2Y (see Fig. 6A) by the energization of a circuit closed from (+), through a circuit including front contact 190 of relay 4NR¹, back contact 191 of relay 2R, and winding of relay 2Y, to (-). The back contact 191 of relay 2R in the pick-up circuit for relay 2Y determines that the track switch 2TS is free to be operated to its normal position as would be required in the establishment of a route having an entrance point at signal 4. The picking up of relay 2Y closes a branch of the initiating circuit network extending to the windings of relays 7XR and 8XR to provide that either of such relays can be picked up at the end of the cycle for designation of a corresponding exit point during which the execution relay XZ is energized.

15 The designation of an exit point for a route which has its entrance point designated at signal 4 causes the transmission of an exit control code subsequent to the cycle required for the transmission of the entrance control for that route. For the purpose of illustration, assume that an operator depresses the button 9XB (see Fig. 2A) for the designation of an exit point for a route having an entrance point previously designated for signal 4. The reception of a control code at the field station in accordance with the exit point designated causes the picking up of the execution relay 9XZ (see Fig. 6A) in a manner similar to that which has been described for the energization of the relay 4XZ (see Fig. 5B), and the picking up of relay 9XZ during the execution period of that cycle causes the picking up of relay 9XR (see Fig. 6A), because that relay has already had its circuit partially conditioned upon the picking up of relays 4NR¹ and 2Y, by the energization of a circuit closed from (+), through a circuit including front contact 190 of relay 4NR¹, back contact 191 of relay 2R, front contact 192 of relay 2Y, winding of relay 9XR, back contact 194 of relay 9NR¹, and front contact 193 of relay 9XZ, to (-). The picking up of relay 9XR closes a stick circuit at front contact 195 to shunt contacts 193 and 194 out of the circuit just described, thus providing that relay 9XR is maintained energized dependent for deenergization upon the opening of front contact 190 of relay 4NR¹. Relay 9XZ is deenergized at the end of the execution period during which it is picked up by the opening of its circuit at front contact 145 of relay LV¹ (see Fig. 5A), and that relay is dropped away after sufficient time is provided by its slow action for the picking up of exit relay 9XR.

20 25 30 35 40 45 50 55 60 65 70 75 The picking up of relay 9XR causes the picking up of relay 2N (because that relay is pre-selected in preference to relay 2R by the picked up position of the preselecting relay 2Y) by the energization of a circuit closed from (+), through a circuit including front contact 196 of

relay 9XR, front contact 197 of relay 2Y, lower winding of relay 2N, and back contact 198 of relay 2R, to (-). The picking up of relay 2N causes the operation of the switch machine 2SM for that track switch to a normal position in a manner hereinafter described.

The connection of front contact 199 of relay 4CNR¹ in multiple with front contact 199 of relay 4NR¹ in the circuits for relays 2Y and 9XR provides that the establishment of the route designated is effected in a similar manner if a call-on control has been designated for signal 4C by the rotation of button 4NB (see Fig. 2A) in a counterclockwise direction at the control office.

Inasmuch as the relay 2Y is dependent for energization upon the designation of an entrance point at signal 4 or signal 4C, it is believed to be apparent, in accordance with the general principles of this type of self-selecting network, that the designation of an entrance point for a route requiring the reverse position of the track switch 2TS, as is the case if an entrance point is designated at signal 5, causes relay 2Y to remain in a dropped away position, and, upon designation of an exit point for that route at signal 9XR, the picking up of relay 9XZ causes the picking up of relay 9XR, under such conditions, by the energization of a circuit closed from (+), through a circuit including front contact 200 of relay 5NR¹, back contact 201 of relay 2N, back contact 192 of relay 2Y, winding of relay 9XR, back contact 194 of relay 9NR¹, and front contact 193 of relay 9XZ, to (-). The picking up of relay 9XR due to such energization closes a stick circuit for that relay at front contact 195 to shunt contacts 193 and 194 out of the circuit just described.

The picking up of relay 9XR for the establishment of such a route causes the picking up of relay 2R (because the preselecting relay 2Y is dropped away at that time) by the energization of a circuit closed from (+), through a circuit including front contact 196 of relay 9XR, back contact 197 of relay 2Y, lower winding of relay 2R, and back contact 202 of relay 2N, to (-). The picking up of relay 2R, due to such energization, causes the operation of the switch machine 2SM to a reverse position in a manner which will be hereinafter described.

From the examples heretofore described whereby a simple route is established, it is believed that it will be readily apparent how the system is applied to more complex track layouts, and how the picking up of an entrance relay NR¹ in the field causes the energization of preselecting relays Y for the various track switches, the energization of such Y relays being rendered effective successively, starting with the Y relay for the track switch nearest the designated entrance point in a route emanating from the point. Inasmuch as the proper positioning of the preselecting relays Y is essential to the proper selection of a route having its entrance and exit points designated, it is desirable that sufficient time be given for the positioning of the relays Y responsive to the designation of an entrance point prior to the designation of an exit point by the picking up of an execution relay XZ for such point. Such time interval is provided in accordance with the present invention by requiring the transmission of entrance and exit controls during separate cycles of operation of the communication system.

Switch control.—Each of the track switches TS is positioned in accordance with the normal relay

N or reverse relay R energized for that track switch through the medium of a polar neutral switch control relay WZ and lock relays including detector route locking and approach locking as required in practice. The use of a polar neutral relay WZ in the control of each track switch provides desirable features in the control of such track switch such, for example, as the follow-through of the operation of each track switch when such operation has been initiated, irrespective of the restoration of the switch control relays N or R for that track switch, and the provision that the track switch may be reversed in mid-stroke to cause its restoration to the position from which it was last operated.

Thus, the picking up of the relay 2N in the establishment of a route from signal 4 or signal 4C to signal 6 causes the picking up of relay 2WZ (assuming the normal conditions of the system to exist as they are illustrated in Fig. 7) by the energization of a circuit closed from (+), through a circuit including front contact 203 of relay 2N, and upper winding of relay 2WZ, to (-). The picking up of relay 2WZ due to such energization causes energy to be applied at polar contacts 204 and 205 to the control circuit for the switch machine 2SM for the operation of that switch machine to a normal position. After the track switch has completed its operation to a normal position in accordance with the position selected for the route having its ends designated, the correspondence relay 2NCR is picked up by the energization of a circuit which has heretofore been described.

If the relay 2R is picked up in the establishment of a route from signal 5 to signal 6, the picking up of that relay causes the energization of the lower winding of relay 2WZ by a circuit closed from (+), through a circuit including front contact 32 of relay 2R, and lower winding of relay 2WZ, to (-). Such energization causes the picking up of relay 2WZ with its polar contacts operated to a left hand position, and thus causes the application of energy to the switch machine 2SM of a polarity selected by contacts 204 and 205 of relay 2WZ to cause the operation of that switch machine to a reverse position. After the operation of the switch machine has been completed to a reverse position in accordance with the relay 2R picked up, the correspondence relay 2RCR is energized by a circuit closed from (+), through a circuit including back contact 203 of relay 2N, winding of relay 2RCR, polar contact 33 of relay 2WP in a left hand position, and front contacts 34 of relay 2WP, to (-). The normal correspondence relay 2NCR is dropped away upon the picking up of relay 2R by the opening of back contact 32.

Whenever a relay WZ is picked up, the pick-up circuit for the LS relay for that track switch is opened, but a stick circuit is closed for that relay because of both correspondence relays being de-energized until the track switch is in correspondence with the controls selected by the normal or reverse switch control relay energized for that track switch. For example, the picking up of relay 2R, when the normal conditions exist as they have been described, causes the dropping away of relay 2NCR by opening the circuit for that relay at back contact 32 of relay 2R, and the dropping away of relay 2NCR closes a stick circuit for relay 2LS from (+), through a circuit including front contact 30 of relay 2L, front contact 206 of relay 2LS, back contact 207 of relay 2RCR, back contact 208 of relay 2NCR, and

winding of relay LS, to (-). As soon as the switch has completed its operation to a reverse locked position, relay 2RCR is picked up by the energization of a circuit which has been described and the picking up of that relay causes the dropping away of relay 2LS by opening its stick circuit at back contact 207, its pick-up circuit having been previously opened at back contact 31 by the picking up of relay 2WZ. The dropping away of relay 2LS closes a branch of the signal control circuit network in a manner which will be hereinafter described.

Aside from being responsive to the designation of route ends, the relays N and R are also energized in accordance with their respective N¹ and R¹ relays picked up when a switch control selected by an SML lever in the control office is received at the field station. For example, the picking up of relay 2R¹ when a reverse control is received for track switch 2TS causes the picking up of relay 2R by the energization of a circuit closed from (+), through a circuit including front contact 232 of relay 2R¹, back contact 231 of relay 2N and center winding of relay 2R, to (-). The picking up of relay 2R due to such energization causes the positioning of the track switch 2TS in a manner which has been described. It is believed to be obvious that the closing of front contact 233 upon the picking up of relay 2N¹ causes the picking up of relay 2N and the subsequent operation of the track switch 2TS to its normal locked position.

Inasmuch as relays 2N¹ and 2R¹ are maintained picked up by their stick circuits until a restoration control is received for such relays, the relays 2N and 2R are also maintained energized under such conditions.

All of the foregoing description of the switch control circuits for track switch 2TS as shown in Fig. 7 is to be considered as typical of the circuits provided for each other track switch in the track layout.

Electric locking.—It is to be understood that suitable approach, detector, and route locking is provided in the field in accordance with the requirements of practice, but, in order to simplify the present disclosure the circuits for providing approach and route locking have not been shown. However, normally energized east and west stick locking relays ES and WS are shown in block form (see Fig. 7) and it is to be understood that the circuits for the control of such ES and WS relays are provided in a manner similar to that shown for the control of relays designated by similar letter reference characters in the patent to A. Langdon, Patent No. 2,148,865, dated February 28, 1939, or, if approach locking is required, the circuits for the ES and WS relays can be provided as shown in the patent to C. F. Stoltz, Patent No. 2,115,511, dated April 26, 1938.

Signal controls.—Before a signal can be cleared the entrance and exit relays NR¹ and XR for that route must be picked up; each track switch must be in a locked position corresponding with the route extending between the designated entrance and exit points; and the switch machine for positioning each track switch in that route must be deenergized. Thus each signal control relay G has its circuit selected by correspondence contacts for each track switch included in the route for which such signal is to be cleared, and the signal control circuits also include a back contact of the LS relay for each of those track switches in the route between the designated entrance and exit points to insure that energy is

removed from the switch machine for each of such track switches after it is positioned.

As a typical example of how a signal is cleared responsive to the establishment of a route in accordance with entrance and exit designation as has been described, assume that a route has been established from signal 5 to signal 6 in accordance with the designation of an entrance point at the control office by the depression of button 5NB and the designation of an exit point for that route by the depression of button 9XB (see Fig. 2A). Responsive to such route end designation the relays 5NR¹ and 9XR (see Fig. 6A) at the field station are picked up, and the picking up of relay 9XR causes the picking up of relay 2R and the operation of the switch machine 2SM to a reverse position. When such reverse position is reached, the correspondence relay 2RCR is picked up and the lock relay 2LS is dropped away to remove energy from the switch machine 2SM, and the dropping away of relay 2LS under such conditions causes the picking up of the signal control relay 5G by the energization of a circuit closed from (+), through a circuit including front contact 214 of relay 9XR, back contact 215 of relay 2LS, front contact 216 of relay 2RCR, back contact 217 of relay 2NCR, back contact 218 of relay 5XR, front contact 219 of relay 5NR¹, and winding of relay 5G, to (-). The opening of back contact 220 of relay 5G causes the red lamp in signal 5 to be extinguished and the closing of front contact 220 causes the illumination of the green lamp in that signal.

If a route is established from signal 4 to signal 6 in accordance with entrance and exit designation in a manner which has been described, the relay 4NR¹ is picked up for the entrance point, relay 9XR is picked up for the exit point, relay 2N is picked up to cause the operation of the switch machine 2SM to a normal position, and the relay 2NCR is energized when the track switch 2TS is locked in the normal position. The dropping away of relay 2LS to remove energy from the switch machine 2SM under such conditions causes the picking up of relay 4G by the energization of a circuit closed from (+), through a circuit including front contact 214 of relay 9XR, back contact 215 of relay 2LS, back contact 216 of relay 2RCR, front contact 221 of relay 2NCR, back contact 222 of relay 4XR, front contact 223 of relay 4NR¹, and winding of relay 4G, to (-). The picking up of relay 4G opens back contact 224 to cause the extinguishing of the red lamp in signal 4 and closes front contact 224 to cause the illumination of the green lamp in that signal.

If an operator causes the establishment of a route from signal 4C to signal 6 by the rotation of the entrance button 4NB in a counter clockwise direction for the designation of an entrance point (see Fig. 2A) relay 4CG (see Fig. 6A) is picked up after such route is established by the energization of a circuit closed from (+), through a circuit including front contact 214 of relay 9XR, back contact 215 of relay 2LS, back contact 216 of relay 2RCR, front contact 221 of relay 2NCR, back contact 222 of relay 4XR, back contact 223 of relay 4NR¹, front contact 225 of relay 4CNR¹, and winding of relay 4CG, to (-). The picking up of relay 4CG causes the extinguishing of the red lamp in signal 4C by the opening of back contact 226, and the closing of front contact 226 causes the illumination of the green lamp or yellow lamp, dependent upon the

color provided for a call-on indication in accordance with the requirements of practice.

After considering the circuits just described it is believed to be apparent that similar circuits are provided for the control of the other signals included in the track layout, and such circuits form a circuit network which provides that a minimum number of contacts are required, and that many of the contacts are used in common for the selection of the control circuits for opposing signals.

Restoration to normal.—If initiation for the entrance point of a route established has been for the clearing of a signal other than a call-on signal, the relays associated with the establishment of that route are automatically restored to normal upon passage of a train past the entering signal to that route, or are restored to normal upon designation at the control office for such restoration by the pulling out of the button for the entrance end of that route. The passage of a train past the entrance end of a route causes the restoration of the entrance relay NR^1 for the entrance to that route by the opening of the front contact of the track relay included in the stick circuit for that entrance relay such, for example, as the dropping away of relay $2TR$ opens the stick circuit for relay $5NR^1$ at front contact 152 (see Fig. 5B). If restoration has been designated by an operator at the control office, by the pulling out of an entrance button, such, for example, as the entrance button $5NB$ (see Fig. 2A), the stick circuit for relay $5NR^1$ (see Fig. 5A) is opened in a manner which has been heretofore described during the execution period for the reception of such restoration control upon the opening of back contacts 163 and 153 of relays $1ST$ and B respectively in the stick circuit for relay $5NR^1$.

The restoration of the relay NR^1 for the entrance end of a route by the opening of the stick circuit for that relay causes the dropping away of the exit relay XR . When such exit relay XR is dropped away the pick-up circuits are opened for the normal and reverse switch control relays for the track switches in that route, and such normal and reverse switch control relays are dropped away, unless restoration is rendered effective upon passage of a train. In that case the relays N and R for each track switch in the route are maintained energized until the train has passed out of the detector track section for that track switch. The signal governing entrance to a route is restored to stop upon the dropping away of its signal control relay G which has its control circuit opened upon the dropping away of the entrance relay NR^1 for the entrance end of that route.

To consider a specific example of the manner in which restoration is provided responsive to the pulling out of an entrance button, assume that an operator pulls out the entrance button $5NB$ (see Fig. 2A) at the control office and causes the dropping away of relay $5NR^1$ (see Fig. 6A), when a route is established from signal 5 to a signal 6 and signal 5 is cleared, the dropping away of relay $5NR^1$ causes the dropping away of the signal control relay $5G$, and the dropping away of that relay opens the circuit for the illumination of the green lamp in signal 5 at front contact 220 and closes a circuit for the red lamp in that signal at back contact 220 . The dropping away of relay $5NR^1$ also causes the dropping away of the exit relay $9XR$ by opening the stick circuit for that relay at front contact

230 , and the dropping away of relay $9XR$ causes the dropping away of relay $2R$ by the opening of the circuit for that relay at front contact 196 . The dropping away of relay $2R$ opens the circuit for relay $2WZ$ at front contact 32 (see Fig. 7) and when relay $2WZ$ is dropped away relay $2LS$ is picked up by the energization of a circuit which has already been described, after relay $2L$ is picked up by the energization of a circuit closed from $(+)$, through a circuit including front contact 26 of relay $2ES$, front contact 21 of relay $2TR$, front contact 28 of relay $2WS$, winding of relay $2L$, back contact 221 of relay $2R^1$ and back contact 228 of relay $2N^1$, to $(-)$, thus completing the restoration of the relays associated with the establishment of that route to their normal positions.

If the relay $5NR^1$ is dropped away because of the passage of a train past that entrance point, restoration is effective in the same manner as that just described except that the relay $2R$, instead of being dropped away when relay $9XR$ is deenergized is maintained picked up by its stick circuit (see Fig. 7) until the detector track section $2T$ becomes unoccupied to allow the picking up of the lock relay $2L$. The relay $2R$ is maintained energized under such conditions by a stick circuit closed from $(+)$, through a circuit including back contact 229 of relay $2L$, front contact 238 of relay $2R$, back contact 231 of relay $2N$, and center winding of relay $2R$, to $(-)$. When relay $2TR$ is picked up, the relay $2L$ is picked up by the energization of a circuit which has been described. The picking up of relay $2L$ due to the energization of that circuit causes the stick circuit for that relay to be closed, such stick circuit having been already described when considering the normal conditions of the system. The picking up of relay $2L$ causes the dropping away of relay $2R$ by opening the stick circuit for that relay at back contact 229 , and the relay $2WZ$ is deenergized by the dropping away of relay $2R$ upon the opening of front contact 32 to cause that relay to be dropped away, and to close the pick-up circuit for relay $2LS$ to complete the restoration to normal of the route establishing means for that route.

It is believed from the foregoing detail description of how the route establishing means is restored for a particular route that it will be apparent how restoration is effective for each of the other routes under similar conditions for initiation of such restoration. If a route is established from signal $4C$ to signal 6 , however, the entrance relay $4CNR^1$ can be dropped away only upon the designation of a restoration control for that entrance point at the control office, in accordance with the stick circuit provided for that relay in a manner which has heretofore been described when considering the reception of controls at the field station. Such type of control provides that signal $4C$ is a non-stick signal, which can be cleared if the track section $2T$ is occupied.

If an operator attempts to establish a route from signal 4 to signal 6 , however, when track section $2T$ is occupied, such route will not be established because the stick circuit for relay $4NR^1$ is held open at front contact 152 of relay $2TR$, thus providing that, although relay $4NR^1$ can be momentarily energized, during the execution period, it is dropped away at the end of the cycle, thus rendering the reception of a control for defining an exit point for the route ineffective.

It is to be understood that other types of track circuit control can be applied to the control of the signals in accordance with the requirement of practice.

If a track switch has been positioned in accordance with the positioning of a lever SML at the control office, such track switch is maintained in that particular position until a restoration control is received at the field station corresponding with the actuation by an operator of the lever SML for that track switch back to its neutral center position. If such restoration control is received at the field station relay N¹ or R¹ energized for that track switch is dropped away in a manner which has been described when considering the reception of controls at the field station, and the restoration of that relay causes the dropping away of the relay WZ for that track switch which, when dropped away, causes the relay 2LS to be picked up to complete the restoration to normal conditions of the switch control relays.

As a specific example of the above conditions assume that relay 2R¹ has been picked up and the track switch 2TS operated to a reverse position in accordance with the operation of the lever 2SML (see Fig. 2B) to an upper position. When a restoration control is received at the field station in accordance with the restoration of the lever 2SML at the control office to its neutral center position the relay 3R¹ is dropped away by the opening of the stick circuit for that relay at back contacts 182 and 185 of relays B and 3ST respectively (see Fig. 5B) and the dropping away of relay 2R¹ causes relay 2R to be dropped away by the opening of the circuit for that relay at front contact 232. The relay 2R, when dropped away, causes the restoration of relays 2WZ and 2LS to their normal positions in the same manner as has been described. It is believed to be obvious that restoration is effective in a much similar manner when relay 2N¹ has been picked up in accordance with the designation of a normal position for the track switch 2TS by the positioning of the lever 2SML at the control office.

Prevention of preconditioning.—Inasmuch as the electric locking for a track switch may be momentarily ineffective if there is a momentary loss of shunt during passage of a train over that track switch, it is provided that a control designated requiring a track switch to be operated to a position contrary to the position in which it is locked by the route or approach locking is ineffective for causing that track switch to be operated. In other words, when a track switch is locked by electric locking in a normal position, the reception of a control for a reverse position of that track switch, or for a route requiring that track switch to be in a reverse position, is ineffective even after such track switch has had its electric locking released. Such mode of operation is generally called in practice "lever lock equivalents."

The preconditioning of routes by entrance and exit control is prevented by the maintaining of the N and R relays picked up as long as their track switches are electrically locked, and thus opening the pick-up circuit for each exit relay XR when a route is not available between a designated entrance point and that exit point.

The preconditioning of track switches by auxiliary lever SML is prevented by providing that each lock relay L can be picked up to release the locking for its track switch only when both

relays N¹ and R¹ controlled in accordance with the lever SML for that track switch are dropped away. Thus, for example, with reference to Fig. 7, relay 2L can be picked up only when relay

5 2N¹ and 2R¹ are dropped away to close a circuit from (+) through a circuit including front contact 26 of relay 2ES, front contact 27 of relay 2TR, front contact 28 of relay 2WS, winding of relay L, back contact 227 of relay 2R¹ and back contact 228 of relay 2N¹ to (-).

End-to-end control.—The system of end-to-end control as shown in Figs. 6A and 6B corresponds with the system shown in the application of Wight and Langdon, Ser. No. 245,384, filed December 13, 1938, to which reference can be made for a more detailed description of the system.

In accordance with such system of end-to-end control the designation of an entrance point causes the positioning of the Y relays for certain of the trailing switches included in each through route emanating from that entrance point, such Y relays being successively energized, starting with the Y relay for the track switch nearest the designated entrance point. Under such conditions, if there are a number of intermediate signals in the through route, it may take considerable time for the preselecting relays Y to respond, dependent of course upon the number of relays to be energized and the characteristics of such relays. In any case, in accordance with the present invention, the relays Y will have sufficient time to be conditioned responsive to the designation of an entrance point before an exit point is designated, as such time space is measured by the length of a cycle of operation of the communication system which generally takes several seconds. It is therefore provided by the present invention that sufficient time is always provided between the time of designation of entrance and exit points to allow the proper response of the preconditioning relays Y, even under the conditions encountered in practice requiring the successive energization of a maximum number of relays. If an exit relay were allowed to pick up before the Y relays were properly conditioned, in some complex track layouts, an undesirable condition might be encountered in which the system might attempt to select a wrong route.

In general, in accordance with the principles of the system of end-to-end control, the designation of an entrance point, in addition to causing the positioning of certain of the Y relays, feeds energy through a through route initiating circuit network to the winding of each exit relay for each exit point that can be included in an available route emanating from the entrance point designated. Such a circuit arrangement conditions each exit relay XR for energization if an exit point is designated by the picking up of its exit execution relay XZ, irrespective of the number of intermediate signals that may be included between such exit point and the entrance point designated. The picking up of an exit relay XR for an exit point designated in the establishment of a route by end-to-end control causes the selection of the proper position for the track switches in the route extending between that exit point and the next intermediate signal included in that through route toward the designated entrance point, and the completion of the selection of such portion of the through route causes the energization of a relay XP for the next intermediate signal toward the designated entrance point

which, in picking up, causes the picking up of the entrance relay for such intermediate signals and the exit relay for the adjacent portion of the through route extending toward the designated entrance point, as if such entrance and exit points had been actually designated by an operator at the control office. The picking up of an exit relay **XR** for an intermediate exit point causes the establishment of a route between that exit point and the designated entrance point, or the next intermediate signal toward the designated entrance point, as the case may be in accordance with a cycle of operations similar to those which have been described in general as being effective responsive to the designation of the exit end of the through route. In this manner the through route is established in steps, one step at a time, each step consisting in the establishment of a route extending between an exit point and the next entrance point (for traffic in the direction corresponding with the route being established) toward the designated entrance point.

To consider as a specific example how a route is established by end-to-end control in the field responsive to the designation of entrance and exit point for that through route at the control office, assume that an operator designates an entrance point for signal **4**, and an exit point for signal **7**. Such designation causes the transmission of entrance and exit controls respectively during separate cycles of operation, and the picking up of relay **4NR¹** when an entrance control for that entrance point is received at the field station causes the picking up of the relay **2Y** (see Fig. 6A) by the energization of a circuit which has been described, and the picking up of that **Y** relay conditions the initiating circuit network in such a manner that the relay **7XR** can be picked up when relay **7XZ** is picked up upon reception of an exit control for that point by the energization of a circuit closed from (+), through a circuit including front contact **190** of relay **4NR¹**, back contact **191** of relay **2R**, front contact **192** of relay **2Y**, back contact **234** of relay **9XR**, wire **235**, back contact **236** of relay **6NR¹**, back contact **237** of relay **3R**, winding of relay **7XR**, front contact **238** of relay **7XZ**, and back contact **239** of relay **7NR¹**, to (-). The picking up of relay **7XR** due to the energization of that circuit closes a stick circuit for that relay at front contact **240** to shunt contacts **238** and **239** of relays **7XZ** and **7NR¹** respectively out of the circuit just described.

When relay **7XR** is picked up, under such conditions, relay **3N** is picked up by the energization of a circuit closed from (+), through a circuit including front contact **241** of relay **7XR**, upper winding of relay **3N**, and back contact **242** of relay **3R**, to (-). The picking up of relay **3N** causes the picking up of the through route relay **6XP** by the energization of a circuit closed from (+), through a circuit including front contact **241** of relay **7XR**, front contact **243** of relay **3N**, winding of relay **6XP**, and back contact **244** of relay **6NR¹**, to (-). A stick circuit is closed for relay **6XP** upon the picking up of that relay from (+), through a circuit including front contact **241** of relay **7XR**, front contact **243** of relay **3N**, winding of relay **6XP**, front contact **245** of relay **6XP**, wire **246**, and back contact **247** of relay **9XR**, to (-).

When relay **6XP** is picked up, relay **6NR¹** is picked up by the energization of a circuit closed from (+), through a circuit including front contact **248** of relay **3TR**, back contact **249** of relay **B** connected in multiple with back contact **250** of relay **5ST**, front contact **251** of relay **6XP**, and

upper winding of relay **6NR¹**, to (-). When relay **6NR¹** is picked up, a circuit is closed for the energization of exit relay **9XR** (see Fig. 6A) from (+), through a circuit including front contact **190** of relay **4NR¹**, back contact **191** of relay **2R**, front contact **192** of relay **2Y**, winding of relay **9XR**, back contact **194** of relay **6NR¹**, wire **252**, front contact **253** of relay **6NR¹**, and front contact **254** of relay **6XP**, to (-). The picking up of relay **9XR** closes a stick circuit at front contact **195** to shunt contacts **194**, **253** and **254** out of the circuit just described.

When relay **6NR¹** is picked up, the circuit heretofore described for the energization of relay **7XR** is opened at back contact **236** and energy is applied to that circuit at front contact **236** to provide that relay **7XR** is dependent upon relay **6NR¹** for energizing the same as if the route had been established from signal **6** to signal **7** by designation by an operator of each of those route ends. Back contact **255** of relay **6XP** is connected in multiple with back contact **236** in the circuit for relay **7XR** to provide that relay **7XR** is maintained energized during the picking up of relay **6NR¹** to close front contact **236**. When relay **9XR** is picked up, relay **6XP** is dropped away because of the opening of its stick circuit at back contact **247**.

The picking up of relay **9XR** by the energization of the circuit described above causes the establishment of a route extending between signal **4** and signal **6** and the clearing of signal **4** in the same manner as has been heretofore described. After the track switch **3TS** is positioned in accordance with the picked up position of the relay **3N**, relay **6G** is picked up for the clearing of signal **6** in accordance with the general principles of the signal control circuits as they have been set forth when considering the signal controls in detail.

After a route is completely established by end-to-end control, each section of that through route extending from one signal to the next signal in advance for governing traffic in the same direction has its route establishing means conditioned as if the entrance and exit buttons for that particular portion of the through route have been actuated, and restoration of such route establishing means to normal is effected in accordance with the general principles of restoration of the system as they have been heretofore pointed out.

Having described the control of a particular remote track layout in accordance with the operation of an entrance-exit type machine at a control office as one specific embodiment of the present invention, it is desired to be understood that this form is selected to facilitate in the disclosure of the present invention rather than to limit the number of forms which the invention may assume; and, it is to be further understood that various adaptations, alterations and modifications may be applied to the specific form shown in accordance with the requirements of practice, without in any manner departing from the spirit or scope of the present invention except as limited by the appending claims.

What I claim is:

1. In a switch and signal control system of the character described for the communication of entrance and exit controls from a control office to a field station for the governing of the establishment of routes through a track layout providing a plurality of conflicting routes extending between entrance and exit points; manually operable contact means at the control office for

each of the entrance and exit points; a communication system effective when initiated to transmit entrance and exit controls designated by the actuation of said contact means to the field station; a change relay at the control office for each entrance point; a change relay at the control office for each exit point; circuit means responsive to the actuation of said contact means for each entrance point for energizing said change relay for that point; circuit means responsive to the actuation of said contact means for each exit point for energizing said change relay for that point; a lockout relay at the control office for each of the entrance and exit points; a circuit network for the energization of each of said lockout relays comprising circuit selections providing for the energization of said lockout relay for each entrance point in preference to the energization of said lockout relay for each exit point when the change relays are contemporaneously energized for entrance and exit points, only one of said lockout relays being energized at any one time; and circuit means responsive to the energization of any one of said lockout relays for initiating said communication system for the transmission of controls designated in accordance with the actuation of said contact means for that point.

2. In a switch and signal control system of the character described for the setting up and restoration of any desired route extending through a track layout between entrance and exit points at a field station remotely located from a control office, such points being defined by the location of wayside signals, each location constituting a control station; manually operable contact means at the control office for designation of entrance, exit, and restoration controls; a transmitter at the control office effective, when said contact means is actuated for any given control station, to transmit to the field station a series of selected impulses providing a code characteristic of such given control station and a code characteristic of the entrance, exit or restoration control designated by the actuation of said contact means; a control station relay at the field station for each of the control stations; an entrance and an exit relay at the field station for each of the respective entrance and exit points; a restoration relay at the field station; code receiving means at the field station responsive to said transmitter effective to energize each of said control station relays in accordance with the control station code of selected impulses transmitted from the control office, only one control station relay being energized at any one time, such code receiving means also being effective to energize each of said entrance and exit relays in accordance with the respective entrance or exit code of selected impulses transmitted from the control office, only if said control station relay for that signal location is energized, and such code receiving means also being effective to energize said restoration relay whenever a restoration code of selected impulses is transmitted from the control office; stick circuit means effective upon the picking up of each of said entrance relays at the field station for maintaining such relay energized dependent for deenergization upon the joint energization of said restoration relay and said station relay for that signal location; and route establishing means responsive to the joint energization of said entrance and exit relays for the opposite ends of each route for causing the setting up of such route, such

route establishing means being maintained effective dependent upon the energized condition of said entrance relay for the entrance end of such route.

- 5 3. In a switch and signal control system of the entrance-exit type for governing the operation of power-operated switches and indications of signals of a railway track layout to provide different traffic routes, manually operable entrance and exit push buttons at a control office associated respectively with each of the signal locations of the track layout and operable to designate the corresponding signal location as either the entrance or the exit end of a desired route; a normally-at-rest code type communication system connecting the control office with the remote track layout and operable to transmit during each cycle of operation over the same line wires a series of impulses to select a designated one of said signal locations and to transmit to that signal location either an entrance or an exit control; initiating means in the control office responsive to the operation of any given push button to initiate a cycle of operation of said communication system to select the corresponding signal location and to create an entrance or exit control, said initiating means being effective upon actuation of entrance and exit buttons for train movement in either direction over any given route to cause an operating cycle for an entrance control prior to an operating cycle for an exit control; and route establishing means for governing the power operation of the track switches to establish any desired route and clear the signal at the entrance end thereof in response to the reception of entrance and exit controls over said code communication system on separate cycles of operation only if an entrance control is received prior to an exit control.
- 10 4. In a switch and signal control system of the entrance-exit type for establishing routes over a track layout and controlling the indications of signals governing train movement over such routes, route establishing means adjacent to the track layout including an entrance relay and an exit relay associated with each signal location of the track layout, said route establishing means being operable to govern the power operation of the appropriate switches to the required position to establish any desired route and clear the signal at the entrance end thereof in response to the energization of the entrance relay and the exit relay for that route, each exit relay after energization thereof assuming its deenergized condition after a limited time, manually operable entrance and exit buttons at a remote control office belonging to each signal location, a code type communication system responsive to the manual actuation of said control buttons to transmit over the same line wires during each of different operating cycles a series of code impulses to select a designated one of the signal locations and cause temporary energization of either an entrance relay or an exit relay for that signal location, said communication system including means in the control office for causing an operating cycle for the transmission of an entrance control prior to an operating cycle for an exit control upon actuation of entrance and exit buttons for train movement in either direction over any given route, a stick circuit for maintaining each entrance relay of the route establishing means energized after the temporary energization thereof by the code communication system, and means associated with each entrance button

and operable to govern the code transmitted during a cycle of operation selecting the corresponding signal location and cause opening of said stick circuit of the corresponding entrance relay.

5. In a switch and signal control system of the entrance-exit type for governing the power operation of track switches and clearing of signals of a railway track layout, a miniature track diagram of said track layout in a remote control office, entrance and exit control buttons on said track diagram at points corresponding with signal locations and manually operable to designate any given signal location as the entrance or exit end of a desired route, a normally-at-rest code type communication system operable in response to the actuation of said control buttons to transmit from the control office to the track layout over the same line wires during a cycle of operation a series of impulses to select a single designated signal location and create either an entrance or an exit control for that signal location, said communication system including starting

and code determining relay means in the control office associated with said control buttons and energized in response to the manual actuation thereof for initiating operation of the communication system and causing transmission of an entrance or an exit control to the corresponding signal location, means for rendering the energization of a relay means in response to the actuation of an exit control button effective to prevent the subsequent energization of all other such relay means in response to the actuation of their corresponding control buttons until after the series of impulses including said exit control has been transmitted, and route establishing means operable in response to transmission of entrance and exit controls over said communication system to govern the power operation of the appropriate switches to establish a route between corresponding entrance and exit signal locations and to clear the signal at the entrance end of that route.

CLARK A. PICKELL.
